CODED RAILWAY SIGNALING SYSTEM

Arthur L. Jerome, Edgewood, Pa., assignor to The
Union Switch & Signal Company, Swissvale,
Pa., a corporation of Pennsylvania

Application March 2, 1944, Serial No. 524,708

11 Claims. (Cl. 246—38)

My invention relates to coded railway traffic controlling apparatus.

In application for Letters Patent of the United States, Serial No. 412,279 of James J. Van Horn, now Patent No. 2,344,333, granted March 14, 1944, there is shown a signaling system for use on stretches of single track over which traffic may move in either direction. In the system of the Van Horn application each track section is provided with two track circuits, one for each direction of traffic, while the system operates so that when traffic is established for either direction coded energy is supplied to the rails of each track section at the exit end thereof and operates the track circuit apparatus for that direction of traffic to control the wayside signals. The system of the Van Horn application is also arranged so that on movement of a train through the track stretch steady energy may be supplied to the stretch at the entrance end thereof and operates the apparatus of the track circuits for the other direction of traffic to cause the steady energy to be cascaded through the stretch to the exit end of the stretch to discontinue the supply of coded energy to the stretch when the stretch is vacated.

In some situations, it is desirable to provide means for indicating at the exit end of each section when that section is occupied. This means may be employed for any appropriate purpose as, for example, to control the supply of energy to the lamps of the wayside signal for the adjacent track section in advance, or to control the supply of coded alternating current cab signal control energy to the section rails.

It has heretofore been proposed to govern approach control means by feed-back energy supplied to the rails of a track section in the intervals between impulses of master code supplied over the section rails.

It is an object of this invention to provide for each track circuit of a track section having two track circuits, one for each direction of traffic, approach control facilities governed by feed-back energy.

Another object of the invention is to provide in a signaling system of the type shown in the Van Horn application, approach control facilities operated by feed-back energy for each direction of traffic in each track section.

A further object of this invention is to provide a system of the type described which is arranged so that the approach control facilities for either direction of traffic are not operative until that direction of traffic has been established.

Another object of the invention is to provide

for a track section track circuit apparatus of the type described which is arranged so that neither master code nor feed-back energy employed in the track circuit for one direction of traffic will interfere with the track circuit apparatus for the other direction of traffic.

A further object of the invention is to provide for a track section track circuit apparatus of the type described which is arranged so that the track circuit apparatus for either direction of traffic will not be improperly operated by energy stored in the section rails as a result of the supply to the section rails of master code or feed-back energy to the track circuit for either direction of traffic.

15 Another object of the invention is to provide coded track circuit apparatus of the type described which is arranged so that one approach control relay serves for one track section when traffic is established for one direction and serves for the adjoining track section when traffic is established for the other direction of traffic.

A further object of the invention is to provide a system of the type described which incorporates means for energizing the approach control relays 20 when neither direction of traffic is established in the track stretch.

Another object of the invention is to provide apparatus of the type described and arranged to 25 reduce or eliminate establishment of the approach controlled circuits on a change in the established direction of traffic in the track stretch.

A further object of the invention is to provide for use in a system of the type described front and back contact coding cut-section apparatus.

35 Another object of the invention is to provide for use in a system of the type described equipment for use at a highway crossing to control the crossing signals and to also control the supply 40 of coded cab signal control energy to the approach sections to the highway intersection.

Other objects of the invention and features of novelty will be apparent from the following description taken in connection with the accompanying drawings.

I shall describe one form of apparatus embodying my invention together with modifications thereof which I may employ, and shall then point out the novel features thereof in claims.

50 Similar reference characters refer to similar parts in each of the several views.

In the drawings,

Figs. 1A and 1B, when placed together with Fig. 1B at the right, form a diagram of a track section and the adjacent ends of the two adjoin-

ing track sections equipped with signaling apparatus embodying my invention;

Fig. 2 is a fragmentary diagram showing means which may be employed in place of that shown in Fig. 1;

Fig. 3 is a diagram showing apparatus which may be employed at a cut-section where back contact coding is employed;

Fig. 4 is a diagram showing apparatus which may be employed at a cut-section where front contact coding is employed; and

Figs. 5A and 5B, when placed together with Fig. 5B at the right, form a diagram of apparatus which may be employed at a highway intersection.

Referring to Figs. 1A and 1B of the drawings, there is shown a stretch of railway track having track rails 1 and 2 which are divided by insulated joints 3 into track sections for signaling purposes. One complete track section designated 5T, and portions of the adjacent ends of the adjoining track sections designated 4T and 6T, are shown. For purposes of illustration it will be assumed that the right-hand end of the track stretch is east and that the left-hand end of the stretch is west so that train movements from left to right are eastbound while train movements from right to left are westbound.

The track stretch is equipped with coded signaling apparatus of the type shown in the above identified application of James J. Van Horn, while the track circuits have been modified to provide for the supply of feed-back energy over the section rails to control energization of approach control relays which govern the supply of coded alternating current cab signal control energy to the section rails, and to also control the supply of energy to the lamps of the wayside signals.

The construction and operation of the locomotive cab signal apparatus governed by the coded alternating current supplied to the track rails is not a part of this invention and this equipment may be constructed as shown in Letters Patent of the United States No. 1,986,679, issued January 1, 1935, to Lloyd V. Lewis.

The alternating current supplied to the section rails may be supplied from a commercial source and may be distributed throughout the track stretch by a transmission line, not shown, while the terminals of this source are designated BX and CX in the drawings.

Each signal location is provided with a source of direct current, such as a storage battery not shown, the terminals of which are designated B and C in the drawings.

As explained in the Van Horn application, when the track stretch is conditioned for eastbound traffic, coded energy is supplied at the east end of the track stretch and is cascaded through the various track sections to the west end of the stretch to cause a signal at that point to display a permissive indication. Similarly, when the track stretch is conditioned for westbound traffic, coded energy is supplied at the west end of the track stretch and is cascaded through the various track sections to the east end of the stretch to cause the signal at that point to display a permissive indication. In addition, on movement of a train through the track stretch in either direction steady energy may be supplied to the stretch and is cascaded through the stretch behind the train to cut off the supply of coded energy over the rails of the various track sec-

tions and to indicate at the exit end of the section when the stretch is vacated.

The equipment is shown in Figs. 1A and 1B in the condition which it assumes when the stretch is vacant and is conditioned for eastbound traffic.

At this time, energy of 180 code frequency is supplied to the rails of section 6T at the right-hand or exit end thereof. As explained in connection with section 5T, this energy is supplied from a track battery and is of such polarity that the positive terminal of the battery is connected to the lower rail 2. This energy feeds from track rail 2 over back contact 10 of coding relay 15 6WCTM, winding of track relay 6ETR from left to right, back contact 11 of relay 6EIR, track winding 12 of relay 6WFB, and back contact 14 of coding relay 6ECTM to track rail 1. This energy picks up the contact of track relay 6E'R, while it moves the contact of polar stick relay 20 6WFB to its left-hand or normal position.

The track relays are all of the polar biased neutral type the contacts of which become picked up when and only when energy flows through the 25 relay winding in a particular direction, while each of these relays is arranged so that its contact is picked up on flow of energy through the relay winding in the direction indicated by the arrow on the relay.

The feed-back detector relays FB are of the 30 polar stick type, the contacts of which are moved to one position by energy of one polarity and are moved to their other position by energy of the other polarity, while the contacts of these relays 35 when moved to either position remain in that position until energy of the polarity effective to move the relay contact to its other position is supplied to the relay.

The circuits for supplying energy to the rails 40 of a section from the track and feed-back batteries at an end of the section are arranged so that the positive terminal of one of these batteries is connected to one track rail and the positive terminal of the other battery is connected 45 to the other track rail. Accordingly, energy of one polarity is supplied to the section rails from one battery and energy of the other polarity is supplied to the section rails from the other battery and to identify the polarity of the energy intended these have been designated normal and 50 reverse polarity.

Similarly, at each end of each section there are two track relays, one of which responds to 55 energy of one polarity supplied over the track rails, that is, to energy supplied when the positive terminal of the source is connected to one track rail, while the other relay responds to energy of the other polarity supplied over the track rails, that is, to energy supplied when the 60 positive terminal of the source is connected to the other track rail, and to identify the polarity of the energy intended these have been designated normal and reverse polarity.

The terms normal and reverse polarity are 65 purely arbitrary designations and either track rail may be connected to the positive terminal of the source to provide energy of normal polarity, but the batteries and track relays at both ends of a section must be arranged in the correct relationship to each other.

On picking up of relay 6ETR energy is supplied over its front contact 15 to slow releasing relay 6EFS, while on release of relay 6ETR energy is supplied over back contact 16 of relay 70 6ETR, front contact 16 of relay 6EFS, and back

contact 17 of relay 5WFSA to relay 6TM, and the contacts of relay 6TM pick up so that energy is supplied over its front contact 18 to slow release relay 6BSA. Accordingly, relay 6BSA is picked up and its contact 20 establishes the circuit for supplying energy to the primary winding of decoding transformer 6DT so that on coding operation of relay 6TM energy is induced in the transformer secondary windings. Energy from one of these secondary windings is rectified by a contact of relay 6TM, as explained in Letters Patent of the United States No. 2,237,788, issued April 8, 1941, to Frank H. Nicholson and Leslie R. Allison, and is supplied to slow release relay 6H, while energy from the other secondary winding is supplied through a resonant rectifier unit 180DU to relay 6J. As relays 6H and 6J are picked up, energy may be supplied over front contact 22 of relay 6H and front contact 23 of relay 6J to the green lamp G of signal 6SE. However, as hereinafter explained, as long as section 5T is vacant, relay 6FBP is picked up and its contact 24 interrupts the circuit of the lamps of signal 6SE.

On continued code following operation of track relay 6ETR, energy is supplied to relay 6EFSA each time the track relay picks up, while each time the track relay releases, energy is supplied to relay 6TM and it picks up to supply energy to relay 6BSA. The relays FSA and BSA are of a type the contacts of which are slow to release so that the contacts of these relays remain picked up in the periods during which the supply of energy to the relays is interrupted. Similarly, the relay 6H is of a type the contacts of which are slow to release so that its contacts remain picked up in the intervals between energy impulses supplied from the decoding transformer.

On release of the contact of the track relay 6ETR, energy is supplied to relay 6TM and its contacts pick up. The relay 6TM does not pick up instantaneously and in the period from release of track relay 6ETR until picking up of relay 6TM, energy is supplied to relay 6EIR over back contact 15 of the track relay 6ETR, front contact 16 of relay 6EFSA, back contact 17 of relay 5WFSA, asymmetric unit 52, back contact 53 of relay 6TM, front contact 54 of relay 6H, front contact 56 of relay 6EFSA, back contact 57 of relay 5WFSA, and back contact 59 of relay 6WCTM. The energy supplied to relay 6EIR picks up its contact 11 so that energy is supplied from battery 6EBB to the rails of section 6T. The energy from the battery 6EBB flows from the positive terminal of the battery over front contact 11 of relay 6EIR, through the winding of track relay 6ETR from right to left, and over back contact 10 of relay 6WCTM to track rail 2, while the negative terminal of this battery is connected over back contact 14 of relay 6WCTM to track rail 1. The energy supplied from battery 6EBB flows through the winding of the track relay 6ETR in the wrong direction to pick up the relay contact while, as explained in connection with section 5T, the energy supplied from battery 6EBB to the rails of section 6T feeds to the east end of the section and operates the feed-back detector relay at that point.

The supply of energy to relay 6EIR is interrupted as soon as relay 6TM picks up, but sufficient energy is supplied to relay 6EIR in the period from release of relay 6ETR to picking up of relay 6TM to pick up the relay contacts. A resistor 60 is connected across the terminals of the winding of the relay 6EIR, while a resistor

61 is connected from the energizing circuit for relay 6EIR to terminal C. The resistors 60 and 61 provide snubbing circuits for the relay 6EIR, and on interruption of the circuit of the relay, delay release of the relay contacts for a period long enough to insure that feed-back energy will be supplied to the rails of section 6T for a period sufficient to operate the feed-back detector relay, but short enough to insure that the relay 6EIR will release before the start of the next "on" period in the code supplied to section 6T.

On release of relay 6EIR, the supply of energy from battery 6EBB to the rails of section 6T is cut off and relays 6ETR and 6WFB are connected

15 in series across the rails of section 6T. Because of the inductance of the track circuit of section 6T, on interruption of the circuit of the battery 6EBB energy may continue to flow in the track circuit in the same direction as it was flowing when energy was supplied from the battery to the track circuit. If this energy continues to flow after contact 11 becomes released, energy will flow from rail 2 to rail 1, over back contact 14 of relay 6WCTM, track winding 12 of relay 25 6WFB from right to left, back contact 11 of relay 6EIR, winding of relay 6ETR, and back contact 10 of relay 6WCTM to rail 2. This energy is ineffective to pick up the contact of relay 6ETR, while it may move the contact of relay 6WFB to 30 its right-hand or reverse position, but this is not objectionable since the circuit controlled by the contact of relay 6WFB is open at front contact 63 of relay 6WS. The arrangement of the track circuit is such that neither the supply of feed-back energy to the section rails nor energy stored 35 in the track circuit as a result of the supply of feed-back energy thereto will interfere with the proper operation of the track circuit apparatus.

If contact 11 of relay 6EIR should engage its 40 front and back contacts simultaneously, the battery 6EBB will be connected to the track winding 12 of relay 6WFB and its contact will be moved to its normal or open position, while any energy supplied to relay 6ETR will flow through the relay winding in the wrong direction to pick up the relay contact. Accordingly, overlapping contacts 45 on relay 6EIR cannot create a hazardous condition.

As relay 6BSA is picked up, its contact 26 establishes a circuit for the code transmitter 180CT and it operates to provide coded energy of 180 code frequency. Energy of 75 code frequency is supplied by a continuously operating code transmitter 75CT.

55 At this time, energy is supplied to the directional stick relay 6ES over the circuit which includes front contact 21 of relay 6H, back contact 28 of relay 5WFSA, and front contact 29 of relay 6EFSA, so the contacts of relay 6ES are picked up and its contact 30 interrupts the circuit of relay 6WCTM and its contacts remain released to connect track relay 6ETR across the rails of section 6T.

The directional stick relay 6WS is released at 65 this time and energy of 180 code frequency is supplied to coding relay 5ECTM over back contact 32 of relay 5WFSA, a contact of code transmitter 180CT, front contact 33 of relay 6H, and back contact 34 of relay 6WS, and the relay 70 5ECTM operates at the 180 code speed. On picking up of the relay 5ECTM, its contacts 36 and 37 connect the track battery 5ETB and the secondary winding of track transformer 5ETT in series across the rails of section 5T with the positive terminal of the battery connected to track

rail 2. The energy from the track battery 5ETB feeds over the rails of section 5T and over back contacts 39 and 40 of relay 5WCTM and picks up the contact of the track relay 5ETR, while this energy also feeds over back contact 42 of relay 5EIR and through the track winding 43 of relay 5WFB so that the contact of this relay is moved to its left-hand or normal position.

In addition, on picking up of relay 5ECTM, its contact 45 establishes a circuit to energize the local winding 46 of relay 5EFB and the relay 5WIR in series so that the contact 48 of relay 5WIR picks up, while the direction of flow of energy through winding 46 of relay 5EFB is such that the contact 49 of the relay is moved to its reverse position in which it interrupts the circuit of relay 6FBP.

The relay 5WIR has a resistor 50 connected across the terminals of its winding, and this resistor is of relatively high resistance so that it delays release of the contact of relay 5WIR for a very short period on interruption of the circuit of the relay winding.

When relay 5WIR picks up, its contact 48 connects the feed-back battery 5WBB in series with the track relay 5WTR but, as the contacts of relay 5ECTM are picked up, no energy flows in this circuit at this time. On release of relay 5ECTM its contact 45 interrupts the circuit for energizing relays 5WIR and 5EFB in series and the contact 49 of relay 5EFB remains in its reverse position, while the contact 48 of relay 5WIR remains picked up for a short period because of the snubbing action of resistor 50 on the relay winding. When contacts 36 and 37 of relay 5ECTM engage their back contacts, the battery 5WBB is connected across the section rails in series with the winding of relay 5WTR, while the direction of flow of energy from the battery 5WBB through the track relay is such as to hold the relay contacts released. The supply of energy from battery 5WBB to relay 5WTR is cut off on release of relay 5WIR which occurs very soon after release of the contacts of relay 5ECTM.

As previously explained, when relay 5ECTM is picked up, the track battery 5ETB is connected across the section rails with the positive terminal of the battery connected to rail 2. When relay 5ECTM releases, the supply of energy from the battery 5ETB to the section rails is interrupted, and because of the inductance of the track circuit energy may continue to flow therein in the same direction that it had been flowing. When contacts 36 and 37 of relay 5ECTM engage their back contacts, inductive energy from the track circuit tends to flow from rail 2 through the ballast, and through the wheels and axles of a train if the section is occupied, to rail 1, thence over back contact 37 of relay 5ECTM, through winding of relay 5WTR from right to left, front contact 48 of relay 5WIR, battery 5WBB, and back contact 36 of relay 5ECTM to rail 2. This energy flows through the winding of the track relay 5WTR in the proper direction to pick up the relay contact, but at this time energy from battery 5WBB flows through the winding of relay 5WTR in the opposite direction and prevents picking up of the relay contact.

Inductive energy from the track circuit, when present at all, persists for only a very short period after interruption of the circuit of the track battery. The desired protection against operation of relay 5WTR by this energy is obtained if relay 5WIR remains picked up and maintains the supply of energy from battery 5WBB through the

winding of relay 5WTR until the inductive discharge from the track circuit terminates, and the resistor 50 is of such value as to delay release of relay 5WIR for a period slightly greater than that required for inductive energy from the track circuit to be dissipated.

The arrangement of the track circuit apparatus is such, therefore, that energy stored in the track circuit as a result of supply of energy therefrom to the track battery 5ETB when the stretch is conditioned for eastbound traffic will not cause improper operation of the track relay 5WTR for the track circuit which is employed when the stretch is conditioned for westbound traffic.

15 The coded energy supplied from battery 5ETB to the rails of section 5T as a result of coding operation of relay 5ECTM feeds to relay 5ETR and operates it so that relays 5EFSA, 5BSA, 5ES, 5H and 5J are picked up, while on each movement 20 of the contact of track relay 5ETR to its released position energy is supplied to relay 5EIR during the pick-up time of relay 5TM as explained in connection with relay 6EIR. Accordingly, during each "off" period in the master code supplied to section 5T, the relay 5EIR picks up and energy is supplied from the battery 5EBB to the rails of section 5T. This energy flows from the positive terminal of the battery over front contact 42 of relay 5EIR, winding of relay 5ETR from 25 right to left, back contact 40 of relay 5WCTM, track rail 2, back contact 36 of relay 5ECTM, track winding 65 of relay 5EFB from left to right, back contact 48 of relay 5WIR, winding of relay 5WTR from left to right, back contact 37 of relay 30 5ECTM, track rail 1, and back contact 39 of relay 5WCTM to the negative terminal of the battery.

The energy supplied from battery 5EBB to relay 5EFB moves the contact 49 of the relay to its left-hand or normal position so that energy is 40 supplied to relay 6FBP over the circuit which includes contact 49, front contact 66 of relay 6ES, and back contact 63 of relay 6WS. During the picked-up periods of the relay 5ECTM, energy is supplied to the local winding 46 of relay 5EFB, 45 as previously explained, and contact 49 is moved to its right-hand or reverse position in which it interrupts the circuit of relay 6FBP. The relay 6FBP is of a type the contacts of which are slow to release so the relay contacts remain picked up 50 in the periods during which the supply of energy to the relay is cut off. Accordingly, contact 24 of relay 6FBP interrupts the circuit of the lamps of signal 6SE, while contact 68 short-circuits the primary winding of track transformer 5ETT over 55 the circuit which is traced from terminal CX over front contact 69 of relays 6ES and transformer primary winding to terminal CX. As a result alternating current is not supplied to the rails of section 5T at this time, while short-circuiting of 60 the track transformer primary winding reduces arcing at the contacts of relay 5ECTM.

At this time, energy of 180 code frequency is supplied to relay 4ECTM over a circuit corresponding to that traced for relay 5ECTM so that 65 energy of 180 code frequency is supplied to the rails of section 4T, while the equipment for section 4T operates in the same manner as that for section 5T with the result that coded energy is supplied to the adjacent section in the rear and feed-back energy is supplied over the rails of section 4T to operate relay 4EFP and energize relay 5FBP to interrupt the circuit of the lamps of signal 5SE and short-circuit the primary winding of the track transformer 4ETT.

70 As explained in the Van Horn application identi-

tified above, coded energy is cascaded through the other track sections to the entrance end of the track stretch to cause the eastbound signal at that point to display a proceed indication and authorize an eastbound train to enter the track stretch.

When an eastbound train enters the track stretch, the rails of the section at the entrance end of the stretch are shunted and the signal at the entrance to the track stretch is caused to display its stop indication, while the equipment at that point may operate to supply steady energy to the west end of the stretch.

When the train advances into section 4T, the supply of feed-back energy over the section rails is cut off and the contact 10 of relay 4EFB is not moved to its normal position to establish the circuit of relay 5FBP and the contacts of relay 5FBP release so that energy is supplied over its back contact 11, front contact 12 of relay 5ES, front contact 13 of relay 5H, and front contact 14 of relay 5J to the green lamp G of signal 5SE. As relay 5WS is released, its contact 16 interrupts the circuit of the lamps of signal 4SW and they remain dark. Also on release of relay 5FBP its contact 17 interrupts the circuit short-circuiting the primary winding of track transformer 4ETT, while energy is supplied to this winding over the circuit which is traced from terminal BX of the source of alternating current over back contact 11 of relay 5FBP, front contact 19 of relay 5ES, and primary winding of transformer 4ETT to terminal CX of the source of alternating current. Accordingly, on continued operation of the coding relay 4ECTM, coded alternating current is supplied to the rails of section 4T to operate the cab signal apparatus on the locomotive present in that section.

When the train advances into section 5T, the supply of coded energy over the rails of section 5T is cut off and contact 49 of relay 5EFB remains in its right-hand or reverse position so that it interrupts the circuit of relay 6FBP and the contacts of relay 6FBP release to complete the circuit of the green lamp G of signal 6SE and to establish the circuit for supplying energy to the track transformer 5ETT.

When section 5T is occupied, the track relay 5ETR remains released and its contact 80 does not establish the circuit of relay 5EFSA so its contacts release with the result that contact 81 interrupts the circuit of relay 5TM and its contacts remain released and relays 5H, 5J and 5BSA release. On release of relay 5H, its contact 13 interrupts the circuit of the green lamp G and establishes the circuit of the red lamp R of signal 5SE.

On release of relay 5EFSA its contact 83 interrupts the pick-up circuit for relay 5ES, while the stick circuit is established for relay 5ES and includes back contact 84 of relay 5EFSA and front contact 85 of relay 5ES. The relay 5ES is of a type the contacts of which are slow to release so contact 85 maintains the relay stick circuit during movement of the contacts of relay 5ES between their picked-up and released positions. The energy supplied to relay 5ES over its stick circuit keeps the relay contacts picked up so that contact 88 of relay 5ES continues to interrupt the circuit of relay 5WCTM and contact 90 establishes the circuit including back contact 91 of relay 4WFSA, a contact of code transmitter 15CT, back contact 83 of relay 5H, and back contact 84 of relay 5WS for supplying energy of 75 code frequency to relay 4ECTM. The relay

4ECTM, therefore, operates to supply energy of 75 code frequency to the rails of section 4T, but until the rear of the train vacates section 4T, this supply of coded energy to the section rails is without effect.

In like manner when the train enters section 6T, the relay 6ETR ceases to follow code and relay 6EFSA releases while energy is supplied to relay 6ES over its stick circuit which includes its own front contact 95 and back contact 96 of relay 6EFSA so the contacts of relay 6ES remain picked up. In addition, at this time, relays 6BSA, 6TM, 6H and 6J release, while energy of 75 code frequency is supplied to relay 5ECTM over the circuit which includes back contact 32 of relay 5WFSA, a contact of the code transmitter 15CT, front contact 99 of relay 6ES, back contact 33 of relay 6H, and back contact 34 of relay 6WS. The relay 5ECTM, therefore, operates to supply energy of 75 code frequency to the rails of section 5T.

When section 6T is occupied, the supply of feed-back energy over the section rails is cut off and the equipment at the exit end of the section operates as explained in connection with section 5T to light the lamps of the signal for the adjacent section in advance and to cause alternating current cab signal control energy to be supplied to the rails of section 6T.

As explained in the Van Horn application identified above, if the equipment at the entrance end of the track stretch is operated to permit a second or following eastbound train to enter the track stretch, steady energy is not supplied to the track rails at the west end of the stretch and coded energy continues to operate the track circuit apparatus. If, when the train under consideration vacates section 4T, steady energy is not supplied to the entrance end of the track stretch, the energy of 75 code frequency supplied to the rails of the section as a result of operation of relay 4ECTM will operate the equipment at the entrance end of the section to cause the signal, not shown, at the entrance end of section 4T to display its yellow or caution indication, while energy of 180 code frequency is supplied to the adjacent section in the rear. The equipment for section 4T operates at this time in the manner explained below in connection with section 5T.

When section 5T is vacated, assuming that steady energy is not supplied at the west end of the stretch, the energy of 75 code frequency supplied to the section rails at the east end of the section feeds to the track relay 5ETR and operates it so that relay 5EFSA picks up to reestablish the circuit of relay 5TM, while relay 5TM operates so that relays 5BSA and 5H pick up and relay 5J remains released. On picking up of relay 5EFSA, its contact 84 interrupts the stick circuit for the relay 5ES, while on picking up of relay 5H energy is supplied to relay 5ES over front contact 100 of relay 5H, back contact 102 of relay 4WFSA, and front contact 83 of relay 5EFSA. The relay 5ES is slow enough in releasing to remain picked up in the period from picking up of relay 5EFSA to picking up of relay 5H. As relays 5ES and 5H are picked up, energy may be supplied over front contact 12 of relay 5ES, front contact 73 of relay 5H, and back contact 14 of relay 5J to the yellow lamp Y of signal 5SE, but if section 4T is vacant, relay 5FBP will be picked up to prevent supply of energy to the lamps of signal 5SE.

At this time, energy of 180 code frequency is

supplied to relay 4ECTM over the circuit which includes back contact 91 of relay 4WFSA, a contact of code transmitter 180CT, front contact 93 of relay 5H, and back contact 94 of relay 5WS, while the code transmitter 180CT is operated by energy supplied over front contact 87 of relay 5BSA.

When relays 5EFSA and 5H pick up, the circuit for supplying impulses of energy to relay 5EIR on release of the contact of relay 5ETR is complete and the relay 5EIR operates to supply impulses of feed-back energy from battery 5EBB to the rails of section 5T during the "off" periods in the master code supplied to the section rails. This feed-back energy operates the relay 5EFB so that its contact 49 establishes the circuit of relay 6FBP and it picks up so that contact 24 interrupts the circuit of the lamps of signal 6SE and contact 68 cuts off the supply of energy to the primary winding of transformer 5ETT and short-circuits this winding.

It will be seen that when the stretch is controlled to permit following train movements, this track circuit apparatus operates to provide appropriate signal indications for the second train and to prevent lighting of the signals and the supply of coded alternating current to the rails of a track section until the section is occupied.

If it is not intended to permit a second train to enter the stretch, steady energy is supplied to the stretch at the entrance end thereof and is cascaded through the various sections in the manner about to be described and cuts off transmission of coded energy through the track stretch.

When section 4T is vacated, steady energy supplied to the section rails at the west or entrance end thereof feeds to relay 4WTR during a released period of the contacts of relay 4ECTM so contact 92 of relay 4WTR picks up and establishes the circuit of relay 4WFSA so its contacts pick up with the result that contact 91 interrupts the circuit traced above for supplying energy of 75 code frequency to relay 4ECTM and the contacts of relay 4ECTM remain released and maintain the circuit of relay 4WTR.

As long as section 5T is occupied, relay 5ES is maintained picked up by energy supplied over its stick circuit which includes back contact 84 of relay 5EFSA and front contact 85 of relay 5ES. As long as relay 5ES is picked up, its contact 88 interrupts the circuit of relay 5WCTM and its contacts remain released with the result that track relay 5ETR is connected across the rails of section 5T, while energy is not supplied from track battery 5WTB to the section rails.

When section 5T is vacated, coded energy supplied from battery 5ETB to the section rails as a result of coding operation of relay 5ECTM feeds over the back contacts 39 and 40 of relay 5WCTM to the track relay 5ETR and picks up its contact 80 so that energy is supplied to relay 5EFSA and its contacts pick up. At this time, relay 4WFSA is picked up so that on picking up of relay 5EFSA energy is not supplied to relay 5TM during released periods of the track relay 5ETR and relay 5H remains released.

When relay 5EFSA picks up, its contact 84 interrupts the stick circuit for relay 5ES and after a brief time interval the contacts of relay 5ES release so that contact 85 of relay 5ES additionally interrupts the relay stick circuit.

On release of relay 5ES at this time, energy is supplied to relay 4ECTM over the circuit which includes front contact 84 of relay 5EFSA, back contact 86 of relay 5ES, back contact 93 of relay

5H, and back contact 94 of relay 5WS. Accordingly, the contacts of relay 4ECTM pick up and interrupt the circuit of relay 4WTR and its contact releases, but as relays 4WFSA and 5EFSA are both picked up no circuit is established on release of relay 4WTR.

In addition, on release of relay 5ES energy is supplied to relay 5WCTM over the circuit which includes front contact 91 of relay 4WFSA, back contact 105 of relay 5WS, back contact 106 of relay 5H, and back contact 88 of relay 5ES. The contacts of relay 5WCTM therefore pick up to connect the battery 5WTB across the rails of section 5T, and to interrupt the circuit of relay 5ETR so that its contact 80 thereafter remains released. The energy supplied from battery 5WTB to the rails of section 5T feeds to track relay 5WTR during a released period of the contacts of relay 5ECTM and picks up contact 108 of relay 5WTR to establish the circuit of relay 5WFSA. Accordingly, the contacts of relay 5WFSA pick up so that its contact 32 interrupts the circuit for supplying energy to relay 5ECTM and the contacts of relay 5ECTM thereafter remain released to maintain the circuit of the relay 5WTR and to discontinue the supply of energy from battery 5ETB to the rails of section 5T with the result that even if the contacts of relay 5WCTM release to connect relay 5ETR across the rails of section 5T, the contact 80 of relay 5ETR will remain released and will not establish the circuit of relay 5EFSA.

As pointed out above, on release of relay 4WTR, the circuit of relay 4WFSA is interrupted, and on release of relay 5ETR the circuit of relay 5EFSA is interrupted, and these relays release after expiration of their release periods.

When relay 4WFSA releases, its contact 91 interrupts the circuit traced above for supplying energy to relay 5WCTM and its contacts release to cut off the supply of energy from battery 5WTB to the rails of section 5T and to connect the track relay 5ETR across the rails of section 5T. However, as pointed out above, at this time relay 5ECTM is released and does not connect battery 5ETB across the rails of section 5T, so that when relay 5WCTM releases and connects track relay 5ETR across the rails of section 5T, the contact of relay 5ETR remains released and does not establish the circuit of relay 5EFSA so the relay 5EFSA releases if it has not already released.

On release of relay 5EFSA, its contact 84 interrupts the circuit traced above for supplying energy to relay 4ECTM and the contacts of relay 4ECTM release and connect relay 4WTR across the rails of section 4T so that steady energy supplied to the section rails at the west end of the section feeds to relay 4WTR and picks up its contact 92 to establish the circuit of relay 4WFSA and cause its contacts to pick up if they have become released, or to remain picked up if they have not become released.

On picking up of the contacts of relay 4WFSA, energy is supplied to relay 5WCTM over front contact 91 of relay 4WFSA, back contact 105 of relay 5WS, back contact 106 of relay 5H, and back contact 88 of relay 5ES, and the contacts of relay 5WCTM pick up to interrupt the circuit of relay 5ETR and connect the battery 5WTB across the section rails. As the circuit of relay 5ETR is interrupted, its contact 80 remains released and does not establish the circuit of relay 5EFSA so the contacts of relay 5EFSA remain released.

As relay 5WCTM is now steadily energized, the battery 5WTB is steadily connected across the rails of section 5T and steady energy is supplied

over the rails of section 5T so that when section 6T is vacated, the equipment at the east end of section 5T operates in the manner just explained to cause steady energy to be supplied to the rails of section 6T.

As previously explained, as long as relay 5ES is picked up, relay 5FBP is connected over back contact 108 of relay 5WS and front contact 109 of relay 5ES to a circuit controlled by contact 70 of relay 4EFB, and to a circuit controlled by contact 110 of relay 4WFSA. As long as section 4T is vacant, the relay 4EFB is operated by feed-back energy supplied over the section rails and contact 70 establishes the circuit to supply energy to relay 5FBP and its contacts are maintained picked up. When section 4T is occupied, relay 4EFB ceases to establish the circuit of relay 5FBP and its contacts release to establish the circuits to light the lamps of signal 5SE and to supply energy to track transformer 4ETT.

When section 4T is vacated, if the stretch continues to be conditioned for eastbound traffic, feed-back energy will again be supplied over the section rails to operate relay 4EFB and cause it to establish the circuit of relay 5FBP so that its contacts pick up to discontinue the supply of energy to transformer 4ETT and to the lamps of signal 5SE.

If, at the time section 4T is vacated, steady energy is supplied to the west end of the stretch and is repeated to section 4T, the relay 4WTR will be operated by this energy and will establish the circuit of relay 4WFSA as explained above. When relay 4WFSA picks up, its contact 110 establishes a circuit including front contact 109 of relay 5ES for supplying energy to relay 5FBP and its contacts pick up.

When section 5T is vacated and relay 5ES releases, as explained above, its contact 109 interrupts the circuit of relay 5FBP and this relay releases. On release of relay 5ES, its contact 79 interrupts the circuit of transformer 4ETT and short-circuits the transformer primary winding, while contact 72 of relay 5ES interrupts the circuit of the lamps of signal 5SE so that release of relay 5FBP is without effect.

The relay 6FBP operates in a similar manner when section 5T is vacated.

If it is now desired to prepare the track stretch for westbound traffic, the steady energy supplied at the west end of the stretch is cut off and coded energy is substituted therefor so that cascading of steady energy through the track stretch is discontinued and coded energy is supplied to the track circuits of the various track sections.

When the energy supplied to the west end of section 4T is changed from steady to coded, the relay 4WTR follows code so that energy is supplied to relay 4WFSA during the picked-up periods of track relay contact 92, while during the released periods of contact 92, energy is supplied over back contact 92, front contact 112 of relay 4WFSA, and back contact 81 of relay 5EFSA to relay 5TM. Accordingly, the contacts of relay 5TM pick up so that energy is supplied to relay 5BSA and its contacts pick up to establish the circuit of the code transmitter 180CT and to also establish the circuit of the primary winding of transformer 5DT so that on continued coding operation of relay 5TM the relays 5H and 5J pick up.

When relay 5H picks up, energy is supplied over front contact 100 of relay 5H, back contact 83 of relay 5EFSA, and front contact 102 of relay

4WFSA to relay 5WS and the contacts of relay 5WS pick up.

In addition, when relay 5H picks up, its contact 106 interrupts the circuit for supplying steady energy to relay 5WCTM and establishes the circuit including back contact 84 of relay 5EFSA and back contact 88 of relay 5ES for supplying energy of 180 code frequency to the relay 5WCTM. Accordingly, relay 5WCTM operates to supply energy of 180 code frequency to the rails of section 5T and relay 5WTR follows code with the result that relay 6TM repeats the track relay and relays 6H and 6J pick up. When relay 6H picks up, energy is supplied to relay 6WS over front contact 27 of relay 6H, back contact 29 of relay 6EFSA, and front contact 28 of relay 5WFSA and the contacts of relay 6WS pick up. When relay 6H picks up, the supply of steady energy to relay 6WCTM is cut off and energy of 180 code frequency is supplied to this relay so that energy of 180 code frequency is supplied to the rails of section 6T. At this time, the code transmitter 180CT is operated by energy supplied over front contact 26 of relay 6BSA so the supply of code to section 6T occurs as soon as relay 6H picks up to establish the circuit of the relay 6WCTM.

On picking up of relay 5H the circuit of relay 4WIR is complete and each time the contact 92 of the track relay 4WTR releases, an impulse of energy is supplied to the relay 4WIR over the circuit which includes back contact 92 of relay 4WTR, front contact 112 of relay 4WFSA, back contact 81 of relay 5EFSA, asymmetric unit 114, back contact 115 of relay 5TM, front contact 116 of relay 5H, front contact 118 of relay 4WFSA, back contact 119 of relay 5EFSA, and back contact 120 of relay 4ECTM. Accordingly, contact 122 of relay 4WIR picks up so that an impulse of feed-back energy is supplied from battery 4WBB through the winding of track relay 4WTR to the rails of section 4T. The resistor 124 connected across the terminals of the winding of relay 4WIR, and the resistor 125 connected to the circuit for supplying energy to relay 4WIR, delay release of relay 4WIR so that the impulse of feed-back energy supplied to the rails of section 4T is of appropriate length.

In like manner when relay 6H picks up, energy is supplied to relay 5WIR over the circuit which includes back contact 108 of relay 5WTR, front contact 17 of relay 5WFSA, back contact 16 of relay 6EFSA, asymmetric unit 52, back contact 53 of relay 6TM, front contact 54 of relay 6H, front contact 51 of relay 5WFSA, back contact 56 of relay 6EFSA, and back contact 45 of relay 5ECTM. Accordingly, contact 48 of relay 5WIR picks up so that an impulse of energy is supplied from battery 5WBB through track relay 5WTR to the rails of section 5T, while the resistor 50 connected across the terminals of relay 5WIR and the resistor 61 associated with the circuit of relay 5WIR delay release of the relay so that the feed-back impulses are of proper duration.

The energy supplied from battery 5WBB to the rails of section 5T feeds to relay 5WFB over the circuit which is traced from the positive terminal of battery 5WBB over front contact 48 of relay 5WIR, winding of relay 5WTR from left to right, back contact 37 of relay 5ECTM, track rail 1, back contact 39 of relay 5WCTM, track winding 43 of relay 5WFB from right to left, back contact 42 of relay 5EIR, winding of track relay 5ETR from right to left, back contact 40 of relay 5WCTM, track rail 2, and back contact 36 of

relay 5ECTM to the negative terminal of the battery 5WBB.

The energy supplied from battery 5WBB to the relay 5WFB flows through the winding 43 of the relay in the direction to move contact 126 to its right-hand or reverse position in which it establishes the circuit for supplying energy to relay 5FBP, while during each picked-up period of the contacts of relay 5WCTM the local winding 127 of relay 5WFB is energized in series with the winding of relay 5EIR over the circuit established by front contact 128 of relay 5WCTM. The energy supplied to the local winding of relay 5WFB moves the contact 126 of the relay to its left-hand or normal position in which it interrupts the circuit of the relay 5FBP.

The energy supplied from the battery 5WBB flows through the windings of track relays 5WTR and 5ETR, but this energy flows through the windings of these relays in the wrong direction to pick up the relay contacts, and operates instead to hold the relay contacts released so there is no danger that the feed-back energy will improperly operate the track relay of either track circuit for section 5T.

Because of the inductance of the track circuit, when the relay 5WIR releases and interrupts the circuit of battery 5WBB, energy may continue to flow in the track circuit. However, this energy flows in the same direction as the energy supplied from the battery and this energy will flow through the winding of track relay 5WTR in the wrong direction to pick up the relay contact. The inductive energy from the track circuit will flow through the track winding 65 of relay 5EFB in the direction to move contact 49 to its left-hand or normal position, but this movement of contact 49, if it occurs, is without effect as the circuit controlled by this contact is open at contact 66 of relay 5ES.

Similarly, when relay 5WCTM releases and interrupts the circuit of battery 5WTR, energy may continue to flow in the track rails because of the inductance of the track circuit, and when the contacts 39 and 40 of relay 5WCTM engage their back contacts, energy from the track circuit will tend to flow to track relay 5ETR and to flow through this winding from left to right, that is, in the direction to pick up the relay contact. However, when the contacts of relay 5WCTM are picked up energy is supplied to relay 5EIR and its contact 42 is picked up to connect battery 5EBB in series with the winding of relay 5ETR with the positive terminal of the battery connected to the right-hand terminal of the relay winding. Accordingly, when the relay 5WCTM releases and connects the track rails with the winding of relay 5ETR, energy from the battery 5EBB flows through the winding of the track relay 5ETR and prevents picking up of the contact of the track relay by inductive energy from the track circuit. At this time, relay 5EIR is snubbed only by resistor 130 so the contact of the relay remains picked up for only a very short period subsequent to interruption of the supply of energy to the relay, and on release of relay 5WCTM the relay 5EIR remains picked up and maintains the supply of energy from battery 5EBB only long enough to prevent operation of relay 5ETR by inductive energy from the track circuit. This inductive energy, when present, is dissipated in a very short period so the relay 5EIR must remain picked up for only a very limited interval, after which it releases and connects relay 5WFB across

the section rails in series with the track relay 5ETR so that the relay 5WFB will respond to feed-back energy supplied over the section rails.

The arrangement of the track circuit apparatus is such, therefore, that when the stretch is conditioned for westbound traffic neither master code nor feed-back energy employed in the track circuits for this direction of traffic will cause operation of the apparatus of the track circuit for the other direction of traffic, while inductive energy from the track circuit occurring on interruption of the circuit of either the track or the feed-back battery will not cause operation of the apparatus of the track circuit for either direction of traffic.

It will be seen that when relay 5H picks up, the supply of steady energy to relay 5WCTM is cut off and coded energy is supplied thereto so that coded energy is supplied to the rails of section 5T and operates relay 5WTR so that relay 6H picks up. As soon as relay 6H picks up, the circuit for supplying energy to relay 5WIR is complete and it operates to supply feed-back energy to the rails of section 5T and thus to relay 5WFB so that contact 126 of relay 5WFB is moved to its right-hand or reverse position in which it establishes the circuit for supplying energy to relay 5FBP.

When relay 5H picks up, its contact 100 establishes the pick-up circuit of relay 5WS and its contacts pick up. When relay 5WS picks up, relay 5FBP is connected over back contact 109 of relay 5ES and front contact 108 of relay 5WS to the circuit controlled by contact 126 of relay 5WFB so that on movement of the contact 126 of relay 5WFB to its reverse position, by feed-back energy, energy is supplied to relay 5FBP to pick up its contacts and maintain them picked up.

In addition, when relay 5WS picks up, its contact 131 interrupts one circuit short-circuiting the primary winding of track transformer 5WT and transfers control of this winding to contact 11 of relay 5FBP. As long as contact 11 of relay 5FBP is picked up, the primary winding of the transformer is short-circuited, while on release of relay 5FBP energy is supplied to the transformer 5WT.

On picking up of relay 5WS, its contact 16 connects the wire leading from the lamps of signal 4SW to contact 11 of relay 5FBP so that on release of relay 5FBP energy is supplied to the lamps of signal 4SW.

When relay 5WS picks up, its contact 84 interrupts the circuit of relay 4ECTM to insure that its contacts will remain released and maintain the circuit of the track relay 4WTR, while contact 105 of relay 5WS establishes the circuit for supplying energy of 75 code frequency to relay 5WCTM on occupancy of section 4T and release of relay 5H.

The equipment at the east end of section 5T operates in substantially the same manner at this time. When relay 6H picks up, energy is supplied to relay 6WS and its contacts pick up to place relay 6FBP under the control of contact 133 of relay 6WFB, and to place transformer 6WT and the lamps of signal 5SW under the control of relay 6FBP.

As pointed out above, when relay 5H picks up, coded energy is supplied to relay 5WCTM and it operates to supply coded energy to the rails of section 5T so that relay 5WTR operates to pick up relay 6H and thereby cause relay 5WIR to operate to supply feed-back energy to the rails

of section 5T to cause contact 128 of relay 5WFB to establish the circuit of relay 5FBP. In addition, when relay 5H picks up, energy is supplied to relay 5WS, and when the contacts of relay 5WS pick up, the relay 5FBP is placed under the control of relay 5WFB, while transformer 5WT and the lamps of signal 4SW are placed under control of the relay 5FBP.

As relay 5FBP is released at the time relay 5WS picks up, energy will be supplied to transformer 5WT and to the lamps of signal 4SW until relay 5FBP picks up. The period required for picking up of relay 5FBP after picking up of relay 5WS may be reduced to a minimum by making the relay 5WS slow to pick up so that relay 5WS will not pick up until after the equipment at the east end of section 5T is conditioned to cause feed-back energy to be supplied to the section rails. This insures that when relay 5WS picks up to place relay 5FBP under the control of relay 5WFB, the relay 5WFB will be operated by feed-back energy so its contact 128 will establish the circuit of relay 5FBP.

The equipment for the other track sections operates in substantially the same manner as that for section 5T so that the supply of coded energy is cascaded through the remaining track sections to the east end of the track stretch to cause the headblock signal at that point to display a permissive indication and thus authorize a westbound train to enter the track stretch.

On movement of a westbound train through the track stretch, the equipment operates in substantially the same manner as it does on movement of an eastbound train through the track stretch, and a detailed description of the operation of the apparatus is unnecessary.

Similarly, when the stretch is being conditioned for eastbound traffic, the equipment operates in substantially the same manner as it does when the stretch is being conditioned for westbound traffic, and a detailed description of the operation of the equipment at such times is unnecessary.

Modification shown in Fig. 2

As explained above, the system shown in Fig. 1 operates so that when traffic is being established for either direction, energy is not supplied to the approach control relays FBP until one or the other of the associated directional stick relays picks up, while when a directional stick relay is picked up and the relay FBP is released, energy is supplied to a track transformer and to the lamps of one of the wayside signals. Accordingly, the system of Fig. 1 operates at such times to cause momentary lighting of the lamps of a wayside signal and momentary supply of cab signal control energy to the track stretch.

It may be desired to eliminate this flashing of the wayside signals and momentary supply of cab signal energy to the track rails, particularly where tuned alternators are employed to supply the alternating current cab signal energy, and Fig. 2 is a diagram showing how this may be accomplished.

Except as hereinafter specifically pointed out the equipment shown in Fig. 2 is the same in construction and operation as the corresponding equipment shown in Fig. 1 at the adjoining ends of sections 4T and 5T.

The equipment of Fig. 2 is shown in the condition which it assumes when the track stretch is vacant and is conditioned for eastbound traffic. At this time, relay 5WS is released so its contact

131 short-circuits the primary winding of track transformer 5WT, while relay 5ES is picked up so that its contact 109A connects relay 5FBP to the circuit controlled by contact 70 of relay 4WFB and by contact 110 of relay 4WFSA, and contact 79 of relay 5ES connects primary winding of track transformer 4ETT to contact 71 of relay 5FBP. As the stretch is assumed to be vacant, feed-back energy supplied over the rails of section 4T moves contact 70 of relay 4WFB to its normal position in which it establishes the circuit of relay 5FBP so that the contacts of relay 5FBP are picked up.

Accordingly, contact 71 of relay 5FBP short-circuits the primary winding of track transformer 4ETT, while contact 71 interrupts the circuit for supplying energy to the lamps of the wayside signals, and contact 135 interrupts the circuit for supplying direct current to the tuned alternator.

20 When an eastbound train enters section 4T, the supply of feed-back energy over the rails of section 4T is cut off and contact 70 of relay 4EFB no longer establishes the circuit of relay 5FBP and its contacts release and contact 135 establishes the circuit for supplying energy to the tuned alternator so that it operates to supply alternating current to the associated transformer, while contact 71 of relay 5FBP connects the primary winding of track transformer 4ETT to the transformer associated with the alternator with the result that coded alternating current is supplied to the rails of section 4T. In addition, on release of relay 5FBP its contact 71 establishes the circuit for supplying energy to the lamps of signal 5SE.

As explained in connection with Fig. 1, steady energy may be supplied to the track stretch after the eastbound train enters the stretch and this energy is cascaded through the various sections as the train advances.

40 When section 4T is vacated and steady energy is supplied over the section rails, track relay 4WTR picks up and its contact 92 establishes the circuit of relay 4WFSA so that its contacts pick up and contact 110 establishes a circuit including front contact 109A of relay 5ES for supplying energy to relay 5FBP. Accordingly, the contacts of relay 5FBP pick up to cut off the supply of energy to the alternator and to the lamps of the wayside signals, while the primary winding of track transformer 4ETT is short-circuited.

When section 5T is vacated, relay 5EFSA is picked up to interrupt the stick circuit for relay 5ES, as explained in connection with Fig. 1, and relay 5ES releases so that its back contact 109B establishes a circuit including back contact 108A of relay 5WS to energize relay 5FBP and its contacts remain picked up to interrupt the circuit of the alternator and of the lamps of the wayside signals. In addition, on release of relay 5ES its contact 109A interrupts the circuits controlled by relays 4WFSA and 4EFB for supplying energy to relay 5FBP, while contact 79 of relay 5ES interrupts the circuit for supplying energy to transformer 4ETT and short-circuits the primary winding of this transformer.

If the stretch is now to be prepared for westbound traffic, the supply of steady energy to the west end of the stretch is cut off, and coded energy is substituted therefor, while as explained in connection with Fig. 1 this coded energy is cascaded through the various track sections.

On the supply of coded energy to track relay 4WTR, energy is supplied over its back contact 92, front contact 112 of relay 4WFSA, and back

contact 81 of relay 5EFSA to the relay 5TM so that it operates to pick up relay 5H and complete the circuit for supplying coded energy to the rails of section 5T, and thus cause the equipment at the right-hand end of section 5T to operate to supply feed-back energy to the section rails to thereby cause contact 126 of relay 5WFB to be moved to its right-hand or reverse position.

In addition, as explained in connection with Fig. 1, when relay 5H picks up, it establishes a pick-up circuit for relay 5WS but relay 5WS is of a type the contacts of which are slow to pick up so the relay does not pick up until after coded energy has been supplied to the rails of section 5T long enough to initiate operation of relay 5WFB by feed-back energy. When relay 5WS picks up, its contact 108A interrupts the circuit including back contact 109B of relay 5ES for energizing relay 5FBP and connects relay 5FBP to the circuits controlled by contact 126 of relay 5WFB, and by front contact 136 of relay 5EFSA. As the stretch is conditioned for westbound traffic, relay 5EFSA is released, while relay 5WFB is operated by feed-back energy supplied over the rails of section 5T so contact 126 of relay 5WFB establishes the circuit of relay 5FBP and keeps its contacts picked up.

As previously pointed out, energy is supplied to relay 5FBP over back contacts of relays 5WS and 5ES until relay 5WS picks up, while relay 5WS is slow to pick up so that track circuit apparatus for section 5T is conditioned to cause feed-back energy to be supplied over the section rails before relay 5WS picks up. At this time, the track circuit apparatus for section 5T is operated by energy of 180 code frequency so there is little delay in the supply of feed-back energy over the section rails. Accordingly, when relay 5WS picks up to interrupt the circuit including back contact 109B of relay 5ES for supplying energy to relay 5FBP and to connect relay 5FBP to the circuit controlled by contact 126 of relay 5WFB, the relay 5WFB is operated by feed-back energy and contact 126 establishes the circuit of relay 5FBP. Furthermore, relay 5FBP is of a type the contacts of which are slow to release so that if at the time relay 5WS picks up, contact 126 of relay 5WFB is in its left-hand or normal position, the contacts of relay 5FBP will remain picked up until contact 126 of relay 5WFB is moved to its reverse position. During preparation of the track stretch for westbound traffic, therefore, relay 5FBP remains picked up and prevents supply of energy to the tuned alternator and to the lamps of the wayside signals.

In like manner, the relay 5FBP remains picked up when the stretch is being prepared for eastbound traffic. The operation of the equipment at such times is substantially the same as when the stretch is being prepared for westbound traffic and a detailed explanation of the operation of the equipment is unnecessary.

Modification shown in Fig. 3

In FIG. 3 of the drawings there is shown cut-section apparatus which may be employed where back contact coding is desired.

As shown in Fig. 3, a track section is divided into two subsections WIT and EVT, each of which is provided with a track circuit for each direction of traffic, while the equipment at adjoining ends of the two sections is arranged so that coded or steady energy supplied to one of these sections will be repeated to the other one of these sections. In addition, each of these track sec-

tions is provided with approach control facilities operated by feed-back energy to govern the supply of alternating current cab signal control energy to the section rails.

Only the equipment at the adjoining ends of the two sections is shown in Fig. 3, and the equipment at the other ends of these sections may be the same in construction and operation as that shown in Fig. 1 or 2.

The apparatus of Fig. 3 is shown in the condition which it assumes when the track stretch is vacant and is conditioned for eastbound traffic. At this time, coded energy is supplied to the rails of section EVT at the right-hand end thereof and this energy feeds over back contacts 140 and 141 of relay E1WCTM, and back contact 142 of relay E1EIR and picks up the contact 146 of track relay E1ETR, and moves the contact of relay E1WFB to its left-hand or normal position.

When relay E1ETR picks up, energy is supplied to relay E1EFSA over back contact 144 of relay W1WFSA, back contact 145 of relay W1WTR, and front contact 146 of relay E1ETR so the contacts of relay E1EFSA are picked up. Accordingly, during the released periods of relay E1ETR, energy is supplied over back contact 144 of relay W1WFSA, back contact 145 of relay W1WTR, back contact 146 of relay E1ETR, and front contact 148 of relay E1EFSA to relay 1BSA so its contacts are picked up.

As relay 1BSA is picked up, its contact 149 interrupts the circuit which it controls for supplying energy to relay 7FBP, while contact 150 establishes a circuit for energizing relay W1ECTM in multiple with relay 1BSA during the released periods of relay E1ETR. The circuit for supplying energy to relay W1ECTM includes back contact 144 of relay W1WFSA, back contact 145 of relay W1WTR, back contact 146 of relay E1ETR, front contact 148 of relay E1EFSA, front contact 150 of relay 1BSA, back contact 151 of relay W1WFSA, and front contact 153 of relay E1EFSA. Accordingly, during each released period of the contact of relay E1ETR energy is supplied to relay W1ECTM and its contacts pick up to supply energy from battery W1ETB to the rails of section WIT, while during the picked-up periods of the contact of relay E1ETR the circuit of relay W1ECTM is interrupted and its contacts release. The relay W1ECTM, therefore, operates to supply to section WIT energy of the same code frequency as that supplied to relay E1ETR, but with the "on" periods in the coded energy supplied to section WIT occurring during the "off" periods in the code supplied to section EVT.

On release of relay E1ETR to establish the circuit of relay W1ECTM the contacts of relay W1ECTM do not pick up instantaneously and, in the period during which they remain released, energy is supplied to relay E1EIR over the circuit which includes back contact 144 of relay W1WFSA, back contact 145 of relay W1WTR, back contact 146 of relay E1ETR, front contact 148 of relay E1EFSA, front contact 150 of relay 1BSA, back contact 151 of relay W1WFSA, front contact 153 of relay E1EFSA, back contact 154 of relay W1ECTM, back contact 155 of relay W1WFSA, and back contact 156 of relay E1WCTM. The supply of energy to relay E1EIR is interrupted as soon as contact 154 of relay W1ECTM picks up, but the energy supplied to relay E1EIR prior to this time picks up the relay contact, while the resistor 157 connected across 75 the terminals of relay E1EIR, and the resistor

158 connected to the energizing circuit for relay E1EIR, delay release of the relay long enough to cause the impulse of feed-back energy supplied to the rails of section E1T to be of adequate duration.

When the contact 142 of relay E1EIR picks up, feed-back energy is supplied from battery E1EBB through the winding of track relay E1ETR to the rails of section E1T. This energy flows through the winding of relay E1ETR in the wrong direction to pick up the contact of this relay, while the energy supplied from the battery E1EBB to the rails of section E1T operates the feed-back detector relay at the right-hand end of section E1T.

When relay W1ECTM picks up, its contact 160 establishes the circuit to energize the relay W1WIR and the lower winding of relay W1EFB in series so the contact 162 of the relay W1EFB is moved to its right-hand or reverse position in which it interrupts the circuit of relay 1FBP. The energy supplied to relay W1WIR picks up its contact 164 so that battery W1WBB is connected in series with the winding of the track relay W1WTR, but as long as relay W1ECTM is picked up, no energy flows from the battery W1WBB.

On release of the relay W1ECTM, contact 160 interrupts the circuit of relays W1WIR and W1EFB, and the relay W1WIR releases after a short time interval determined by the resistor 165 connected across the terminals of the relay winding. In the period after release of relay W1ECTM and prior to release of relay W1WIR, energy is supplied from battery W1WBB through relay W1WTR to the section rails and prevents operation of relay W1WTR by inductive energy from the track circuit occurring on release of the relay W1ECTM and interruption of the circuit of the battery W1ETB. The resistor 165 delays release of relay W1WIR for only a very short period, and on release of contact 164 of relay W1WIR the relays W1EFB and W1WTR are connected in series across the rails of section W1T so that the impulse of feed-back energy supplied over the rails of section W1T at this time moves the contact 162 of relay W1EFB to its left-hand or normal position, but does not pick up the contact of relay W1WTR.

On movement of contact 162 of relay W1EFB to its left-hand position, energy is supplied to relay 1FBP over the circuit including contact 162 of relay W1EFB, back contact 161 of relay W1WFA, and front contact 168 of relay E1EFSA, so the contact 169 of relay 1FBP is picked up to prevent supply of energy to transformer W1ETT and to short-circuit the primary winding of this transformer.

During the picked-up periods of the relay W1ECTM, the contact 162 of relay W1EFB is moved to its reverse position in which it interrupts the circuit of relay 1FBP, but the relay 1FBP is slow enough in releasing to remain picked up during these periods. Accordingly, when the stretch is conditioned for eastbound traffic, the relay 1FBP is connected to the circuit controlled by contact 162 of relay W1EFB, while as long as section W1T is vacant, relay W1EFB is operated by feed-back energy supplied over the section rails and maintains relay 1FBP energized.

When an easbound train enters section W1T, the supply of feed-back energy over the section rails is cut off and contact 162 of relay W1EFB remains in its reverse position in which it inter-

rupts the circuit of relay 1FBP. Accordingly, the contact 169 of relay 1FBP releases and establishes the circuit including front contact 170 of relay E1EFSA for supplying energy to transformer W1ETT so that on continued coding operation of relay W1ECTM, coded alternating current cab signal control energy is supplied to the rails of section W1T to operate the cab signal equipment on the locomotive in that section.

When the train advances into section E1T, the track relay E1ETR is shunted and ceases to establish the circuit of relay E1EFSA and it releases to interrupt the circuit of relay 1BSA so that its contacts release. On release of relay 1BSA, its contact 149 establishes a circuit to supply energy to relay 1FBP and its contact 169 is picked up to prevent supply of alternating current to the circuits controlled by this contact. In addition, on release of relay 1BSA, its contact 150 interrupts the circuits for supplying coded energy to the coding relays and establishes a circuit over which steady energy may be supplied to one or the other of these relays.

On release of relay E1EFSA, its contact 153 interrupts the circuit traced above for supplying coded energy to coding relay W1ECTM, while contact 168 of relay E1EFSA interrupts the circuit controlled by contact 162 of relay W1EFB for supplying energy to relay 1FBP, and contact 170 of relay E1EFSA interrupts the circuit for supplying energy to transformer W1ETT and short-circuits the transformer primary winding.

When section E1T is occupied, the supply of feed-back energy to the section rails is cut off and the equipment at the right-hand end of this section operates to cause coded alternating current cab signal control energy to be supplied to the section rails.

As explained in connection with Fig. 1, on movement of a train through the track stretch steady energy may or may not be supplied to the stretch in the rear of the train depending on whether or not another train is to be permitted to pass through the track stretch.

If steady energy is not supplied to the west end of the track stretch, the equipment will remain as described until section E1T is vacated, at which time coded energy supplied at the right-hand end of the section operates relay E1ETR so that relays E1EFSA and 1BSA are picked up to thereby cause relay W1ECTM to operate as a repeater of relay E1ETR and to place relay 1FBP under the control of relay W1EFB.

If steady energy is supplied to the west end of the stretch, it will be cascaded through the various sections as they are vacated, as explained in connection with Fig. 1. As will be understood from Fig. 1, the equipment at a signal location operates in such manner that steady energy is not supplied to a section until the section is vacated and an impulse of coded energy is supplied over the section rails.

Accordingly, when section W1T is vacated, the equipment for the section remains deenergized until section E1T is vacated and coded energy supplied over the rails of that section operates relay E1ETR to pick up relays E1EFSA and 1BSA so that relay W1ECTM operates to supply coded energy to the rails of section W1T. The coded energy supplied to section W1T at the right-hand end thereof causes the equipment, not shown, at the left-hand end of the section to supply steady energy to the rails of section W1T. During a released period of the contacts of relay W1ECTM,

this energy feeds to relay W1WTR and picks up its contact 145 so that energy is no longer supplied to relays E1EFSA, 1BSA and W1ECTM. Accordingly, the contacts of relay W1ECTM remain released and maintain the circuit of relay W1WTR so that the contact of relay W1WTR remains picked up. After a short time interval, the contacts of relay E1EFSA release so that energy is supplied over back contact 148 of relay E1EFSA, back contact 146 of relay E1ETR, and front contact 145 of relay W1WTR to relay W1WFSA and its contacts pick up. Relay 1BSA also releases at this time so energy is supplied over its back contact 149 to relay 1FBP, while energy is supplied over back contact 150 of relay 1BSA, back contact 153 of relay E1EFSA, and front contact 151 of relay W1WFSA to relay E1WCTM and its contacts pick up to cause steady energy to be supplied to the rails of section E1T, and thus cause steady energy to be repeated throughout the track stretch.

If the steady energy supplied to the west end of the track stretch is cut off and coded energy substituted therefor, this coded energy will be cascaded through the track stretch so that coded energy is supplied to the west end of section W1T. On the supply of coded energy to section W1T the relay W1WTR follows code, and energy is supplied to relay 1BSA during the released periods of the contact of relay W1WTR, and the contacts of relay 1BSA pick up with the result that, during the released periods of relay W1WTR, energy is supplied to coding relay E1WCTM over the circuit which includes back contact 148 of relay E1EFSA, back contact 146 of relay E1ETR, back contact 145 of relay W1WTR, front contact 144 of relay W1WFSA, front contact 150 of relay 1BSA, back contact 153 of relay E1EFSA, and front contact 151 of relay W1WFSA. Accordingly, relay E1WCTM operates as a back contact repeater of track relay W1WTR and causes coded energy to be supplied to the rails of section E1T.

In addition, at this time, energy is supplied to relay W1WIR over the circuit traced above for relay E1WCTM, plus the branch which includes back contact 172 of relay E1WCTM, back contact 173 of relay E1EFSA, and back contact 160 of relay W1ECTM, so the relay W1WIR operates to cause impulses of feed-back energy to be supplied to the rails of section W1T during the "off" periods in the code supplied to that section. The circuit for energizing the relay W1WIR has the resistor 174 associated therewith, and this resistor together with the resistor 165 connected across the terminals of relay W1WIR delays release of the relay enough to cause the feed-back impulses supplied to section W1T to be of proper duration.

The resistor 174 is connected with the circuit at such a point in the circuit that it is isolated from relay E1WCTM as soon as the contacts of relay E1WCTM pick up. This prevents the resistor 174 from affecting the release of relay E1WCTM with resultant distortion of the code supplied to the rails of section E1T.

During the picked-up periods of relay E1WCTM, its contact 156 establishes the circuit to energize relay E1EIR in series with the local winding of relay E1WFB so that contact 142 of relay E1EIR is picked up to connect battery E1EBB in series with the relay E1ETR and thus prevent operation of relay E1ETR by inductive energy from the track circuit on release of relay E1WCTM. On release of relay E1WCTM contact 156 interrupts the circuit of relay E1EIR and connects the relay winding to the wire leading to the back con-

tact 155 of relay W1WFSA. At this time, relay W1WFSA is picked up so contact 155 interrupts connection between the winding of relay E1EIR and the resistor 158, and resistor 158 will not prolong release of relay E1EIR. Accordingly, at this time, the release period of relay E1EIR is determined solely by resistor 151 which may be of such value as to delay release of relay E1EIR for only a short period subsequent to release of relay E1WCTM. This insures that relay E1EIR will remain picked up long enough to prevent operation of relay E1ETR by inductive energy from the track circuit, but also insures that relay E1EIR will release and establish the circuit of relay E1WFB soon enough to make certain that relay E1WFB will be operated by feed-back energy supplied over the section rails.

In like manner, the resistors 158 and 174 are incorporated in the circuit so that they do not interfere with the proper operation of the equipment when the stretch is conditioned for eastbound traffic.

At this time, relay 1BSA is picked up so its contact 149 interrupts the circuit which it controls for supplying energy to relay 1FBP, but at this time relay 1FBP is connected over front contact 161 of relay W1WFSA and back contact 168 of relay E1EFSA to the circuit controlled by contact 175 of relay E1WFB so that on operation of relay E1WFB by feed-back energy the relay 1FBP is maintained picked up to prevent supply of alternating current to the track transformer E1WTB.

On movement of a westbound train through the track stretch, the equipment operates in substantially the same manner as it operates on movement of an eastbound train through the track stretch and a detailed description of the operation of the equipment is unnecessary.

Modification shown in Fig. 4

In Fig. 4 there is shown cut-section apparatus which may be employed at cut-sections where front contact coding is desired.

The equipment shown in Fig. 4 is similar to that shown in Fig. 3 and differs therefrom in that the coding relays WCTM and ECTM are energized over front contacts of the track relays, while the impulse relays are energized over front contacts of the coding relays.

The operation of the equipment shown in Fig. 4 is similar to that shown in Fig. 3. The equipment of Fig. 4 is shown in the condition which it assumes when the stretch is vacant and is conditioned for eastbound traffic. At this time, relay E8ETR is operated by coded energy supplied over the rails of section E8T and during the picked-up periods of the relay contact 179 energy is supplied to relay E8EFSA and to relay W8ECTM, while during the released periods of relay E8ETR the relay W8ECTM releases, and energy is supplied to relay 8BSA and its contacts are picked up so that on release of relay E8ETR energy is supplied to relay E8EIR over the circuit including front contact 181 of relay 8BSA, back contact 182 of relay W8WFSA, front contact 183 of relay E8EFSA, front contact 184 of relay W8ECTM, back contact 185 of relay W8WFSA, and back contact 186 of relay E8WCTM. The supply of energy to relay E8EIR is interrupted as soon as relay W8ECTM releases, but sufficient energy is supplied to relay E8EIR in the period between release of relay E8ETR and release of relay W8ECTM to pick up the relay E8EIR, while the resistors associated with relay E8EIR delay release of its contacts

long enough to insure that the impulses of feed-back energy supplied from battery E8EBB during the picked-up periods of relay E8EIR are of adequate duration.

During the picked-up periods of relay W8ECTM, its contact 187 establishes the circuit to energize relay W8WIR and the local winding of relay W8EFB so the contact 188 of relay W8EFB is moved to its reverse position, while contact 190 of relay W8WIR picks up to connect battery W8WBB in series with the track relay W8WTR to prevent operation of the relay W8WTR by inductive energy from the track circuit.

During the released periods of the contacts of relay W8ECTM, feed-back energy supplied over the rails of section W8T energizes relay W8EFB and moves its contact 188 to its normal position so that energy is supplied over this contact, back contact 191 of relay W8WFSA, and front contact 192 of relay E8EFS to relay WFBP, and its contact is picked up to prevent supply of energy to track transformer W8ETT and to short-circuit the transformer primary winding.

On movement of a train through the stretch, this apparatus operates in a manner similar to the back contact coding equipment shown in Fig. 3, and a detailed tracing of the circuits is unnecessary. Similarly, the equipment operates in a manner similar to that of Fig. 3 on a change in the established direction of traffic.

Modification shown in Fig. 5

In track stretches equipped with signaling apparatus of this type, the approach sections to a highway crossing may be equipped with track circuits employing steady energy and the steady and coded traffic governing energy may be transmitted around these sections by a line circuit.

In these situations it is necessary to provide means for supplying coded alternating current to the rails of the approach sections, and one means for controlling the supply of coded cab signal energy to the approach sections is shown in my application for Letters Patent of the United States, Serial No. 516,363, filed December 31, 1943, now Patent No. 2,357,235, issued August 29, 1944.

As shown in Fig. 5 the track stretch includes a highway intersection which is protected by crossing signals XS, while the track section which includes the intersection is divided into an intermediate section OT which includes the crossing, a westbound approach section EAT, and an eastbound approach section WAT. The remainder of the track section is completed by sections WT and ET.

The track sections WAT, OT and EAT are provided with track circuits employing steady energy, while the sections WT and ET are provided with track circuits employing coded energy. Only the equipment at the ends of the sections WT and ET adjacent the approach sections is shown in the drawings, and the equipment at the other ends of these sections may be arranged as shown in Fig. 1.

The steady and coded traffic governing energy employed in the track stretch is transmitted around the approach sections by means of a line circuit consisting of line wires 200 and 201 which are governed by the track relays of the sections WAT, OT and EAT.

The crossing signals XS are governed by a relay XR which is controlled by the track relays of the sections WAT, OT and EAT, and by directional stick relays WSR and ESR.

The equipment of Fig. 5 is shown in the condition which it assumes when the stretch is vacant and is conditioned for eastbound traffic. At this time, coded energy is supplied to the rails of section ET at the right-hand or east end thereof and feeds to track relay ETR over the circuit which is traced from track rail 1, over back contact 203 of coding relay ETCTM, winding of relay ETR from right to left, back contact 204 of impulse relay EIR, track winding 205 of relay EFB, and back contact 207 of relay ETCTM to rail 2. The energy supplied to the rails of section ET is of the proper polarity to pick up the contacts of relay ETR, while this energy moves the contact 209 of relay EFB to its reverse position.

When relay ETR picks up, its contacts 210 and 211 connect line wires 200 and 201 to the terminals B and C of a source of current so that the positive terminal B is connected to wire 200. The energy supplied to the line wires flows from terminal B over front contact 210 of relay ETR to wire 200, over back contact 213 of relay WTR, winding of coding relay WTCTM from left to right, back contact 214 of relay WIRA, line winding 215 of relay WFBA from left to right, back contact 216 of relay WTR, wire 201, front contact 217 of relay WATR, front contact 218 of relay OTR, front contact 219 of relay EATR, and front contact 211 of relay ETR to terminal C.

The energy supplied over the line wires to coding relay WTCTM picks up its contacts so that energy is supplied from battery WTETB over front contacts 221 and 222 of relay WTCTM to the rails of section WT to operate the equipment at the west end of the section.

When relay WTCTM is picked up, its contact 226 establishes a circuit to energize relay WIR and the local winding of relay WFB in series so that contact 224 of relay WFB is moved to its left-hand or normal position in which it interrupts the circuit of relay WFBP, while contact 228 of relay WIR is picked up to connect battery WBB in series with the winding of relay WTR to thereby prevent operation of relay WTR by inductive energy from the track circuit on release of relay WTCTM as explained in connection with Fig. 1.

On release of relay ETR the supply of energy over the line wires is cut off and the line wires are connected over back contacts 210 and 211 of relay ETR to relays EFBA and ETCTM. At this time the contacts of relay WTCTM release to interrupt the supply of energy from battery WTETB to the rails of section WT, and to interrupt the circuit of relay WIR so that its contact 228 releases to connect relays WTR and WFB across the section rails. Accordingly, feed-back energy supplied over the rails of section WT moves the contact 224 of relay WFB to its right-hand or reverse position in which it establishes the circuit of relay WFBP to thereby cause its contact 225 to be picked up and short-circuit the primary winding of transformer WTT.

As a result of coding operation of relay WTCTM, energy is supplied through the associated decoding transformer to relay WTP and its contact 229 is picked up to permit energy to be supplied to transformer WTT on release of relay WFBP. In addition, impulses of energy are supplied from a secondary winding of the decoding transformer to impulse relay WIRA which is of a type which responds to energy of one polarity only. The apparatus is arranged so that the energy impulses supplied to relay WIRA on

release of relay WTCTM are effective to pick up the contacts of relay WIRA.

Accordingly, on release of relay WTCTM, the contacts of relay WIRA pick up momentarily, with the result that feed-back energy is supplied to the line wires over the circuit which is traced from the positive terminal B of a source over front contact 214 of relay WIRA, winding of relay WTCTM from right to left, back contact 213 of relay WTR, wire 200, back contact 210 of relay ETR, winding of relay ETCTM from right to left, back contact 230 of relay EIRA, line winding 231 of relay EFBPA, back contact 211 of relay ETR, wire 201, front contacts of track relays EATR, OTR and WATR, back contact 216 of relay WTR, and front contact 232 of relay WIRA to terminal C. The energy supplied over the line wires on picking up of relay WIRA flows through the windings of relays WTCTM and ETCTM in the wrong direction to pick up their contacts, and flows through the winding 231 of relay EFBPA in the direction to move the contact 234 of the relay to its right-hand position in which it establishes the circuit of relay EFBPA so that its contact 235 is picked up and interrupts the circuit of transformer EAETT.

At this time, track relay WTR is not responding to coded energy so relay WTRP is released and its contact 236 interrupts the circuit of transformer WAWTT. As relay WTP is picked up, its contact 237 interrupts the circuit for supplying impulses of energy to relay WIR from the decoding transformer associated with relay WTR, while contact 231 also interrupts connection between relay WIR and resistor 238 so the release time of relay WIR is determined solely by resistor 239.

As relay ETCTM is not responding to coded energy, relay ETP is released and short-circuits the winding of track transformer ETT, while contact 240 of relay ETP establishes the circuit for supplying energy to relay EIR from the decoding transformer associated with relay ETR.

As a result of coding operation of relay ETR, energy is supplied through the associated decoding transformer to relay ETRP and its contact 241 is picked up to permit energy to be supplied to transformer EAETT, while each time the contacts of relay ETR release, an impulse of energy is supplied from a secondary winding of the decoding transformer over back contact 240 of relay ETP, and back contact 243 of relay ETCTM to relay EIR to pick up its contact 204 to cause an impulse of feed-back energy to be supplied from the battery EBB through the track relay ETR to the rails of section ET. At this time, relay EIR is snubbed by resistors 244 and 245 so release of its contact is delayed long enough to insure that the feed-back impulse supplied to the rails of section ET is of adequate duration.

On each movement of the contacts of the track relay ETR to their picked-up position, energy is supplied to the local winding 247 of relay EFBPA and moves its contact 234 to its left-hand or normal position in which it interrupts the circuit of relay EFBPA.

It will be seen that as a result of coding operation of track relay ETR the relay ETRP is picked up to permit energy to be supplied to transformer EAETT; relay EIR operates to supply feed-back energy to section ET; energy is supplied to the local winding of relay EFBPA; while the line winding of relay EFBPA is connected across line wires 200 and 201 during the released periods of relay ETR. In addition, as a result of coding operation of relay ETR coded energy is supplied over

the line wires 200 and 201 to operate relay WTCTM and cause coded energy to be supplied to the rails of section WT, while as a result of operation of relay WTCTM, relay WTP is picked up to permit energy to be supplied to transformer WTT; the relay WIRA operates to supply feed-back energy to the line wires 200 and 201 so that relay EFBPA is picked up to prevent supply of energy to transformer EAETT; relay WIR is operated to prevent operation of relay WTR by inductive energy from the track circuit; and relay WFB is operated by feed-back energy and by energy supplied to its local winding to keep relay WFBP picked up to prevent the supply of energy to transformer WTT.

As the stretch is vacant, the relay XR is energized by current supplied over the circuit which includes front contact 250 of relay OTR, front contact 251 of relay EATR, and front contact 252 of relay WATR. Accordingly, contact 253 of relay XR is picked up and prevents operation of the crossing signals XS.

As the track relays WATR, OTR and EATR are picked up, the directional stick relays WSR and ESR are released with the result that the coding relay XCTM is disconnected from the line wires 200 and 201, while the circuits controlled by the coding relay XCTM for supplying coded alternating current to the rails of sections WAT, OT and EAT are interrupted.

When an eastbound train enters section WT, the supply of feed-back energy over the section rails is cut off and the contact 224 of relay WFB remains in its left-hand or normal position in which it interrupts the circuit of relay WFBP. Accordingly, contact 225 of relay WFBP releases to complete the circuit of the primary winding of track transformer WTT so that on continued coding operation of relay WTCTM coded alternating current is supplied to the rails of section WT to operate the cab signal apparatus on the locomotive present in that section.

When the train advances into section WAT, track relay WATR releases and its contact 217 interrupts the supply of coded energy to relay WTCTM and also interrupts the supply of feed-back energy over the line wires 200 and 201 as a result of operation of relay WIRA.

When relay WTCTM ceases to follow code, energy ceases to be supplied through the associated decoding transformer to relay WTP and its contact 229 releases to prevent the supply of energy to transformer WTT and to short-circuit the transformer primary winding.

In addition, on release of relay WATR, its contact 252 interrupts the circuit of relay XR and its contact 253 releases to initiate operation of the crossing signals XS.

On release of relay WATR energy is supplied to relay ESR over the circuit which includes front contact 255 of relay EATR, back contact 256 of relay WATR, and back contact 251 of relay WSR so that relay ESR picks up with the result that coding relay XCTM is connected across the line wires 200 and 201 so as to be operated by energy supplied to the line wires as a result of coding operation of relay ETR. The coding relay XCTM is of a type which responds to energy of one polarity only, and at this time the right-hand terminal of the relay winding is connected over back contact 259 of relay WSR, and front contact 260 of relay ESR to wire 200, while the other terminal of the winding of relay XCTM is connected over back contact 261 of impulse relay XIR, back contact 262 of relay

WSR and front contact 263 of relay ESR to wire 201 at a point intermediate the contacts of relays OTR and EATR in wire 201. The energy supplied from wires 200 and 201 to relay XCTM is of the proper polarity to operate the relay and its contacts operate at the rate determined by the frequency of the coded energy supplied to the wires 200 and 201.

During the picked-up periods of the contacts of relay XCTM, alternating current is supplied to track transformer WAETT over the circuit which includes front contact 265 of relay XCTM, back contact 266 of relay WSR, front contact 267 of relay ESR, and front contact 268 of relay OTR so coded alternating current is supplied to the rails of section WAT to operate the cab signal apparatus on the locomotive present in that section.

On coding operation of relay XCTM, its contact 270 causes the two portions of the primary winding of impulse transformer XIT to be alternately energized so that impulses of energy are supplied to relay XIR. The relay XIR is of a type which responds to energy of one polarity only and the equipment is arranged so that energy of the polarity effective to pick up the contact of relay XIR is supplied to the relay on release of relay XCTM. Accordingly, on release of relay XCTM the contact of relay XIR picks up with the result that feed-back energy is supplied from battery XFB to relay EFBA over the circuit which is traced from the positive terminal of the battery XFB over front contact 261 of relay XIR, winding of relay XCTM from left to right, back contact 259 of relay WSR, front contact 260 of relay ESR, wire 200, back contact 210 of relay ETR, winding of relay ETCTM from right to left, back contact 230 of relay EIRA, line winding 231 of relay EFBA from right to left, back contact 211 of relay ETR, wire 201, front contact 219 of relay EATR, front contact 263 of relay ESR, and back contact 262 of relay WSR to the negative terminal of the battery XFB.

The energy supplied from battery XFB flows through the windings of relays XCTM and ETCTM in the wrong direction to pick up their contacts, while the energy supplied from battery XFB to the line winding 231 of relay EFBA moves the relay contact 234 to its right-hand or reverse position in which it establishes the circuit of relay EFBA so that its contact 235 is picked up to prevent the supply of energy to transformer EAETT. During the picked-up periods of relay ETR, energy is supplied to the local winding 247 of relay EFBA to move the relay contact 234 to its left-hand or normal position in which it interrupts the circuit of relay EFBA.

It will be seen that when an eastbound train enters section WAT the track relay WATR releases to cut off the supply of coded energy to coding relay WTCTM, while relay ESR picks up and connects coding relay XCTM across the line wires 200 and 201 so that it is operated by coded energy supplied to the line wires by relay ETR, and relay XCTM causes coded alternating current to be supplied to the rails of section WAT. When relay WATR releases, the supply of feed-back energy over the line wires as a result of operation of relay WIRA is cut off, but on operation of relay XCTM the relay XIR operates to cause feed-back energy to be supplied to the line wires and this feed-back energy operates relay EFBA to maintain relay EFBA energized and

thus prevent the supply of alternating current to transformer EAETT.

When the train advances into section OT, the relay OTR releases and its contact 268 cuts off the supply of coded alternating current to transformer WAETT and establishes the circuit to supply energy to transformer OETT and therefrom to the rails of section OT to operate the locomotive cab signal apparatus while the train is in section OT. When relay OTR releases, its contact 218 additionally interrupts supply of energy over line wire 201 to relay WTCTM, while contact 250 additionally interrupts the circuit of relay XR and establishes a stick circuit for relay ESR which includes its own front contact 271.

When the train advances into section EAT, track relay EATR releases and its contact 219 cuts off the supply of coded energy from line wires 200 and 201 to relay XCTM and it ceases to operate, while the supply of feed-back energy from battery XFB over the line wires to relay EFBA is cut off and its contact 234 remains in its normal position in which it interrupts the circuit of relay EFBA. Accordingly, relay EFBA releases and its contact 235 establishes the circuit including contact 272 of track relay ETR and contact 241 of relay ETRP for supplying coded energy to track transformer EAETT and therefrom to the rails of section EAT to operate the cab signal apparatus on the locomotive.

When the rear of the train vacates section WAT, track relay WATR picks up and its contact 217 is closed, but the supply of energy over the line wires 200 and 201 to relay WTCTM is prevented by contact 218 of relay OTR and contact 219 of relay EATR so relay WTCTM remains released and does not cause energy to be supplied to the rails of section WT.

When relay WATR picks up, it completes a stick circuit for relay ESR which includes front contact 256 of relay WATR, back contact 255 of relay EATR, and front contact 274 of relay ESR and relay ESR remains energized after the train vacates section OT and track relay OTR picks up so that its contact 250 interrupts the stick circuit which it controls for relay ESR.

When the train vacates section OT and relay OTR picks up, energy is supplied over front contact 250 of relay OTR, front contact 275 of relay ESR, and front contact 252 of relay WATR to relay XR and its contact 253 picks up to discontinue operation of the crossing signals XS.

When relay OTR picks up, the supply of energy over the line wires to relay WTCTM is prevented by contact 219 of relay EATR and relay WTCTM remains released and does not cause energy to be supplied to the rails of section WT.

When the train enters section ET, the track relay ETR remains released and ceases to supply coded energy to the line wires 200 and 201, while energy is no longer supplied through the decoding transformer to relay ETRP and its contact 241 releases to interrupt the circuit of transformer EAETT. In addition, relay EIR ceases to supply feed-back energy from battery EBB to the rails of section ET and the equipment, not shown, at the right-hand end of section ET operates to cause coded alternating current to be supplied to the section rails to operate the locomotive cab signal apparatus.

When the train advances into the section in advance of section ET, the equipment for that section operates to cause the energy supplied to section ET to be changed to energy of 75 code frequency as explained in connection with Fig. 1.

When the train vacates section EAT, track relay EATR picks up and its contact 255 interrupts the previously traced stick circuit for relay ESR and the contacts of relay ESR release to disconnect the coding relay XCTM from the line wires 200 and 201 and to interrupt the circuit for supplying coded alternating current to the transformers OETT and WAETT. In addition, when relay EATR picks up, its contact 251 completes the originally traced circuit for relay XR so that on release of relay ESR, relay XR remains picked up and prevents operation of the crossing signals XS.

When relay EATR picks up, its contact 219 completes the circuit of the line wires 200 and 201, but at this time, relay ETR is released so energy is not supplied to the line wires and relay WTCTM remains released and does not cause energy to be supplied to the rails of section WT.

When the train vacates section ET, coded energy supplied over the section rails picks up the relay ETR so that energy is supplied over its front contacts 210 and 211 to line wires 200 and 201. This energy feeds to relay WTCTM and picks up its contacts so that energy is supplied from battery WTETB to the rails of section WT.

If, at this time, the equipment at the entrance end of the track stretch is conditioned to permit a second or following train to pass through the track stretch, steady energy will not be supplied to the track stretch at the west end thereof and on coding operation of relay WTCTM, the signal, not shown, for section WT will be caused to provide a permissive indication.

When relay WTCTM follows code, relay WTP is picked up to permit energy to be supplied to transformer WTT, while feed-back energy supplied over the rails of section WT operates relay WFB to pick up relay WFBP to prevent the supply of energy to transformer WTT and to short-circuit the transformer primary winding. In addition, as a result of code following operation of relay WTCTM, relay WIRA operates to supply feed-back energy to the line wires 200 and 201 during the released periods of relay ETR, and this energy operates relay EFBA to pick up relay EFBA and thus prevent the supply of energy to transformer EAETT.

As a result of code following operation of relay ETR, the relay ETRP is picked up to permit energy to be supplied to transformer EAETT, while relay EIR operates to supply feed-back energy to the rails of section ET and thus cause the equipment at the exit end of section ET to cut off the supply of alternating current to the rails of section ET.

If, on passage of the first train through the track stretch, the equipment at the entrance end of the stretch is not conditioned to permit a second train to enter the stretch, steady energy will be supplied to the stretch at that point and will be cascaded through various track sections as they are vacated as explained in connection with Fig. 1.

Under these conditions, steady energy is not supplied to section WT until the relay WTCTM operates to supply an impulse of energy from battery WTETB over the rails of section WT to pick up the track relay, not shown, at the entrance end of the section. Accordingly, when an east-bound train passes through the stretch, steady energy is not supplied to section WT until the train vacates section ET and coded energy supplied over the section rails picks up relay ETR to cause energy to be supplied over line wires 200 and 201 to relay WTCTM and thus cause an im-

pulse of energy to be supplied from battery WTETB to the rails of section WT. When this occurs, the equipment, not shown, at the left-hand end of section WT operates, as explained in connection with Fig. 1, to cause steady energy to be supplied to the rails of section WT at the left-hand end thereof.

During a released period of the contacts of relay WTCTM, the steady energy supplied to the rails of section WT feeds to relay WTR and picks up its contacts with the result that the supply of energy from line wires 200 and 201 to relay WTCTM is cut off and the relay WTCTM thereafter remains released and maintains the circuit of relay WTR. In addition, when relay WTR picks up, energy is supplied over its front contacts 213 and 216 to the line wires 200 and 201, the positive terminal of the source being connected to wire 201. This energy feeds from the positive terminal of the source over front contact 216 of relay WTR, wire 201, back contact 211 of relay ETR, winding 231 of relay EFBA, back contact 230 of relay EIRA, winding of relay ETCTM from left to right, back contact 210 of relay ETR, wire 200, and front contact 213 of relay WTR to the other terminal of the source. The energy supplied to relay ETCTM flows through the relay winding in the proper direction to pick up the relay contacts so that its contacts 203 and 207 interrupt the circuit of relay ETR to insure that it remains released and maintains the circuit for supplying energy from the line wires 200 and 201 to relay ETCTM, while steady energy is supplied from battery ETWTB over front contacts 203 and 207 of relay ETCTM to the rails of section ET to cause the equipment, not shown, at the exit end of section ET to operate to repeat the supply of steady energy to the adjacent section in advance when that section is vacated.

At this time, as relay WTCTM is deenergized, relay WTP is released and prevents supply of energy to transformer WTT while, as relay WTR is steadily energized, the relay WTRP is released and prevents the supply of energy to transformer WAWTT. Similarly, as relay ETCTM is steadily energized, relay ETP is released and prevents supply of energy to transformer ETT while as relay ETR is released, relay ETRP is released and prevents supply of energy to transformer EAETT.

If it is now desired to condition the track stretch for westbound traffic, the steady energy supplied to the west end of the stretch is cut off and coded energy is substituted therefor. On the supply of coded energy to the west end of the stretch coded energy is cascaded through the various sections as explained in connection with Fig. 1. On the supply of coded energy to section WT, the relay WTR follows code so that coded energy is supplied to the line wires 200 and 201, while energy is supplied to relay WTRP and its contact 236 is picked up to permit energy to be supplied to transformer WAWTT.

In addition, on code following operation of relay WTR, energy is supplied from the associated decoding transformer to relay WIR to cause it to supply impulses of feed-back energy from battery WBB to the rails of section WT during the "off" periods in the code supplied to section WT. At this time, relay WTP is released and its contact 237 connects resistor 238 to the circuit of relay WIR so that relay WIR is snubbed by resistors 238 and 239 and its release is delayed long enough to insure that the feed-back impulses supplied to the rails of section WT are of adequate duration. The energy supplied from battery WBB to the

rails of section WT flows through the winding of relay WTR in the wrong direction to pick up the relay contacts, while the feed-back energy supplied to the rails of section WT operates equipment, not shown, at the left-hand end of the section to prevent supply of alternating current to the section rails at that point. On release of relay WIR, inductive energy supplied from the track circuit to relay WIR is of the wrong polarity to operate the relay so the relay contacts remain released until master code is supplied over the section rails to the relay winding.

The coded energy supplied to the line wires 200 and 201 as a result of coding operation of relay WTR produces coding operation of relay 15 ETCTM so that coded energy is supplied from battery ETWTB to the rails of section ET, while energy is supplied through the associated decoding transformer to relay ETP and its contact 276 is picked up to permit energy to be supplied to transformer ETT.

As a result of code following operation of relay ETCTM, impulses of energy are supplied from the associated decoding transformer to relay EIRA and its contacts pick up to cause impulses 25 of feed-back energy to be supplied to line wires 200 and 201 during the "off" periods in the master code supplied to these line wires. During the picked-up periods of the contacts of relay EIRA, energy flows from the positive terminal B of the 30 source over front contact 277 of relay EIRA, back contact 211 of relay ETR, wire 201, back contact 218 of relay WTR, line winding 215 of relay WFBA, back contact 214 of relay WIRA, winding of relay WTCTM from right to left, back contact 213 of relay WTR, wire 200, back contact 210 of relay ETR, winding of relay ETCTM from right to left, and front contact 230 of relay EIRA to terminal C of the source.

The energy supplied over front contacts of 40 relay EIRA to the line wires 200 and 201 flows through the windings of relays ETCTM and WTCTM in the wrong direction to pick up the contacts of these relays so they remain released, while this energy flows through the line winding 215 of relay WFBA in the direction to move the relay contact 278 to its right-hand or reverse position in which it establishes the circuit of relay WFBPA so that its contact 279 is picked up to prevent the supply of energy to transformer WAWTT. During the picked-up periods of track relay WTR, energy is supplied to the local winding 281 of relay WFBA to move the relay contact to its left-hand or normal position in which it 45 interrupts the circuit of relay WFBPA.

During the picked-up periods of relay ETCTM, its contact 243 establishes the circuit to energize the relay EIR and the local winding 282 of relay EFB in series to move the contact 289 of relay EFB to its right-hand or reverse position in which it interrupts the circuit of relay EFBP, while the contact 284 of relay EIR is picked up to connect the battery EBB in series with the track relay ETR and thereby prevent operation of relay ETR by inductive energy from the track circuit on release of the contacts of relay ETCTM. At this time, relay ETP is picked up so its contact 248 interrupts connection of resistor 245 with the relay EIR so that relay EIR is snubbed only by resistor 244 and release of its contacts is delayed for only a short period after release of relay ETCTM.

The coded energy supplied to section ET causes the equipment not shown, at the right-hand end of the section to operate to supply impulses

of feed-back energy to the section rails during the "off" periods in the master code supplied to the section. The positive terminal of the feed-back battery is connected to rail 2 so energy flows from rail 2 over back contact 207 of relay ETCTM, track winding 205 of relay EFB from left to right, back contact 204 of relay EIR, winding of relay ETR from left to right, and back contact 203 of relay ETCTM to track rail 1.

The feed-back energy supplied over the rails of section ET flows through the winding of relay ETR in the wrong direction to pick up the relay contacts, but flows through the winding 205 of relay EFB in the direction to move the contact 289 to the position to establish the circuit of relay EFBP so that its contact 284 is picked up to prevent the supply of energy to transformer ETT and to short-circuit the transformer primary winding.

On movement of a westbound train through the track stretch, the equipment operates in a manner similar to that described in detail in connection with movement of an eastbound train through the stretch.

When the westbound train enters section ET, the supply of feed-back energy over the section rails is cut off and relay EFBP releases so that its contact 284 completes the circuit including front contact 276 of relay ETP for supplying energy to transformer ETT and on continued coding operation of relay ETCTM coded alternating current is supplied to the rails of section ET to operate the locomotive cab signal apparatus.

When the train advances into section EAT, track relay EATR releases so that contact 218 prevents supply of coded energy over line wires 200 and 201 to relay ETCTM, while contact 251 interrupts the circuit of relay XR so that it releases and initiates operation of the crossing signals. In addition, on release of relay EATR, energy is supplied to relay WSR over the circuit which includes front contact 256 of relay WATR, back contact 255 of relay EATR, and back contact 274 of relay ESR so that the relay WSR picks up and connects coding relay XCTM across line wires 200 and 201 so that it is operated by coded energy supplied to the line wires over front contacts 213 and 216 of relay WTR. At 45 this time, the right-hand terminal of the winding of relay XCTM is connected over back contact 268 of relay ESR and front contact 259 of relay WSR to wire 201 at a point intermediate contact 211 of relay WATR and contact 218 of relay OTR, while the left-hand terminal of the winding of relay XCTM is connected over back contact 261 of relay XIR, back contact 263 of relay ESR, and front contact 262 of relay WSR to wire 200. The wire 201 to which the right-hand terminal of the winding of relay XCTM is connected is connected over front contact 216 of relay WTR to the positive terminal of the source of current so the coded energy supplied over the line wires to the relay XCTM is of the proper polarity to operate the relay.

On code following operation of relay XCTM, coded energy is supplied to transformer EAWTT over the circuit which includes front contact 265 of relay XCTM, back contact 261 of relay ESR, front contact 266 of relay WSR, and front contact 285 of relay OTR so coded alternating current is supplied to the rails of section EAT to operate the locomotive cab signal apparatus.

In addition, on code following operation of 75 relay XCTM, energy is supplied through trans-

former XIT to relay XIR so that its contact 261 picks up on release of relay XCTM. When relay XIR picks up, energy is supplied from the positive terminal of battery XFB over front contact 261 of relay XIR, winding of relay XCTM from left to right, back contact 260 of relay ESR, front contact 259 of relay WSR, wire 201, back contact 216 of relay WTR, line winding 215 of relay WFBA from right to left, back contact 214 of relay WIRA, winding of relay WTCTM from right to left, back contact 213 of relay WTR, wire 200, front contact 262 of relay WSR, and back contact 263 of relay ESR to the negative terminal of the battery XFB.

The energy supplied from battery XFB flows through the windings of relays XCTM and WTCTM in the wrong direction to pick up the contacts of these relays and their contacts remain released, while the energy supplied from battery XFB flows through winding 215 of relay WFBA in the direction to move contact 218 of the relay to its right-hand or reverse position in which it establishes the circuit of relay WFBA. Accordingly, relay WFBA remains picked up and prevents supply of energy to transformer WAWTT.

When the train advances into section OT, relay OTR releases and its contact 285 cuts off supply of coded energy to transformer EAWTT and establishes the circuit to supply coded energy to transformer OWTT. On release of relay OTR its contact 218 additionally interrupts the line wire 201, while its contact 250 additionally interrupts the circuit of relay XR and establishes a stick circuit for relay WSR which includes its front contact 286. At this time, relay XCTM continues to be operated by coded energy supplied over the line wires 200 and 201, while relay XIR continues to cause impulses of feed-back energy to be supplied to the line wires to operate relay WFBA and maintain relay WFBA energized and thus prevent supply of energy to transformer WAWTT.

When the train advances into section WAT, track relay WATR releases so that its contact 217 cuts off supply of coded energy to relay XCTM and also cuts off supply of feed-back energy over the line wires to relay WFBA so that contact 278 of relay WFBA remains in its left-hand or normal position in which it interrupts the circuit of relay WFBA. Accordingly, contact 279 of relay WFBA releases and establishes the circuit including contact 289 of track relay WTR and front contact 236 of relay WTRP for supplying coded energy to transformer WAWTT and therefrom to the rails of section WAT to operate the locomotive cab signal apparatus.

On continued movement of the westbound train through the track stretch, the equipment operates in a manner similar to that described in connection with movement of an eastbound train through the track stretch and a detailed description of the operation of the equipment is unnecessary.

Although I have herein illustrated and described one form of apparatus embodying my invention, together with several modifications which I may employ, it is understood that various changes and modifications may be made therein within the scope of the appended claims without departing from the spirit and scope of my invention.

Having thus described my invention, what I claim is:

1. In combination, a section of railway track

having a first and a second track rail and through which traffic may move in either direction, a first coding relay at the first end of said section having contacts biased to a first position in which they connect a second code following track relay and a first code following detector relay across the section rails, said coding relay contacts being movable to a second position in which they connect a first track battery across the section rails with the positive terminal of said battery connected to the first track rail, a second coding relay at the second end of said section having contacts biased to a first position in which they connect a first code following track relay and a second code following detector relay across the section rails, the contacts of said second coding relay being movable to a second position in which they connect a second track battery across the section rails with the positive terminal of said battery connected to the second track rail, the first track relay and the first detector relay each having a contact which is moved from a first to a second position when and only when energy flows through the winding of said relay from the first to the second track rail, the second track relay and the second detector relay each having a contact which is moved from a first to a second position when and only when energy flows through the winding of said relay from the second to the first track rail, means for at times supplying coded energy to the first coding relay, means for at other times supplying coded energy to the second coding relay, each of said track relays having associated therewith means responsive to code following operation of the said relay to supply to the section rails through the winding of said track relay impulses of feed-back energy of the polarity effective to cause energy to flow through the winding of the detector relay at the other end of the section in the direction to move the contact thereof from its first to its second position, a first control relay governed by the contact of said first detector relay, and a second control relay governed by the contact of said second detector relay.

2. In combination, a section of railway track through which traffic may move in either direction, a first coding relay at the first end of said section, a second coding relay at the second end of said section, means for at times supplying coded energy to the first coding relay, means for at other times supplying coded energy to the second coding relay, each of said coding relays having normally released contacts which when released connect across the section rails a code following relay responsive to energy of normal polarity and a code following relay responsive to energy of reverse polarity, a source of energy of normal polarity which is connected across the section rails when the contacts of the first coding relay are picked up, a source of energy of reverse polarity which is connected across the section rails when the contacts of the second coding relay are picked up, means responsive to code following operation of the normal polarity code following relay at the second end of the section for supplying impulses of energy of normal polarity to the section rails through the winding of said normal polarity code following relay, means responsive to code following operation of the reverse polarity code following relay at the first end of the section for supplying impulses of energy of reverse polarity to the section rails through the winding of said reverse polarity code following relay, a first control relay governed by the normal polar-

ity code following relay at the first end of said section, and a second control relay governed by the reverse polarity code following relay at the second end of said section.

3. In combination, a stretch of railroad track through which may move in either direction locomotives equipped with cab signal apparatus responsive to flow of coded alternating current in the section rails, said track stretch including a track section having a first coding relay at the exit end of the section for a first direction of traffic and a second coding relay at the exit end of the section for the second direction of traffic, means effective only when the stretch is conditioned for movement of traffic in said first direction to supply coded energy to said first coding relay, means effective only when the stretch is conditioned for movement of traffic in said second direction to supply coded energy to said second coding relay, each of said coding relays having normally released contacts which when released connect across the section rails a code following relay responsive to energy of normal polarity and a code following relay responsive to energy of reverse polarity, a source of energy of normal polarity which is connected across the section rails in series with the secondary winding of a first track transformer when the contacts of said first coding relay are picked up, a source of energy of reverse polarity which is connected across the section rails in series with the secondary winding of a second track transformer when the contacts of said second coding relay are picked up, means responsive to code following operation of the normal polarity code following relay at the entrance end of the section for the first direction of traffic for supplying to the section rails at that end thereof impulses of energy of normal polarity, means responsive to code following operation of the reverse polarity code following relay at the entrance end of the section for the second direction of traffic for supplying to the section rails at that end thereof impulses of energy of reverse polarity, means governed by the normal polarity code following relay at the exit end of said section for the first direction of traffic for supplying energy to the primary winding of said first track transformer, and means governed by the reverse polarity code following relay at the exit end of said section for the second direction of traffic for supplying energy to the primary winding of said second track transformer.

4. In a coded track circuit railway signaling system, a code transmitting and receiving means comprising a coding relay having contacts movable between a first and a second position and biased to their first position in which they connect across the rails of a section of railway track a code following relay responsive to energy of normal polarity and a code following relay responsive to energy of reverse polarity, a source of energy of normal polarity which is connected across the section rails when the coding relay contacts are in their second position, an impulse relay having a normally released contact which when picked up connects a source of current of reverse polarity across the section rails in series with the winding of said reverse polarity code following relay provided the contacts of said coding relay are in their first position, means for supplying energy to said impulse relay when the coding relay contacts are in their second position, and means governed by said reverse polarity code following relay for supplying energy to said impulse relay when

the contacts of said coding relay are in their first position.

5. In a coded track circuit railway signaling system, a code transmitting and receiving means comprising a coding relay having contacts movable between a first and a second position and biased to their first position in which they connect across the rails of a section of railway track a code following relay responsive to energy of normal polarity and a code following relay responsive to energy of reverse polarity, a source of energy of normal polarity which is connected across the section rails when the coding relay contacts are in their second position, an impulse relay having a normally released contact which when picked up connects a source of current of reverse polarity across the section rails in series with the winding of said reverse polarity code following relay provided the contacts of said coding relay are in their first position, a first circuit governed by said reverse polarity code following relay for supplying energy to said impulse relay provided the contacts of said coding relay are in their first position, a second circuit over which energy is supplied to said impulse relay whenever the coding relay contacts are in their second position, means associated with said second circuit for delaying release of said impulse relay for a relatively short period on interruption of said second circuit, and means associated with said first circuit for delaying release of said impulse relay for a longer period on interruption of said first circuit.

6. In a coded track circuit railway signaling system, a code transmitting and receiving means comprising a coding relay having contacts movable between a first and a second position and biased to their first position in which they connect across the rails of a section of railway track a first code following track relay responsive only to energy of reverse polarity and a second code following track relay of the two-position polarized type, a source of energy of normal polarity which is connected across the section rails when the coding relay contacts are in their second position, an impulse relay having a normally released contact which when picked up connects a source of current of reverse polarity across the section rails in series with the winding of said first track relay provided the contacts of said coding relay are in their first position, means effective when the coding relay contacts are in their second position to supply energy to said impulse relay and to also supply to said second track relay energy effective to move its contacts to their reverse position, and means governed by said first track relay for supplying energy to said impulse relay when the contacts of said coding relay are in their first position.

7. In a coded track circuit railway signaling system, a code transmitting and receiving means comprising a coding relay having contacts movable between a first and a second position and biased to their first position in which they connect across the rails of a section of railway track a first code following track relay responsive only to energy of reverse polarity and a second code following track relay of the two-position polarized type, a source of energy of normal polarity which is connected across the section rails when the coding relay contacts are in their second position, an impulse relay having a normally released contact which when picked up connects a source of current of reverse polarity across the section rails in series with the winding of said first track

relay provided the contacts of said coding relay are in their first position, means effective when the coding relay contacts are in their second position to supply to said second track relay energy effective to move its contacts to their reverse position, and means governed by said first track relay for supplying energy to said impulse relay when the contacts of said coding relay are in their first position.

8. In a coded track circuit railway signaling system for use in single track stretches through which traffic may move in either direction, code transmitting and receiving means for the adjoining ends of a first and second section comprising a coding relay for each section having contacts biased to a released position in which they connect across the section rails a code following track relay responsive only to energy of normal polarity and a code following track relay responsive to energy of reverse polarity, the contacts of each coding relay when picked up being effective to connect across the rails of the associated section a source of energy of one polarity, means governed by code following operation of the normal polarity track relay for the first section for supplying coded energy to the coding relay for the second section and for supplying to the rails of said first section coded energy of the polarity opposite to that supplied to the section rails when the contacts of the coding relay for the first section are picked up, and means governed by code following operation of the normal polarity track relay for the second section for supplying coded energy to the coding relay for the first section and for supplying to the rails of said second section coded energy of the polarity opposite to that supplied to the section rails when the contacts of the coding relay for said second section are picked up.

9. In a coded track circuit railway signaling system, code transmitting and receiving means comprising a code following track relay having a contact which is moved from a first to a second position when and only when energy flows through the relay winding in a selected direction, a coding relay having contacts operable between a first and a second position, said coding relay contacts being effective when in their first position to connect a source of direct current across the rails of a section of railway track with the positive terminal of the source connected to the first track rail, said coding relay contacts being effective when in their second position to connect said track relay across the section rails so that energy flowing from the second to the first track rail flows through said track relay winding in said selected direction, an impulse relay having a contact which when picked up connects a source of direct current in series with the winding of said track relay in such manner that energy from said source flows through the track relay winding in the reverse of said selected direction, and means effective when the coding relay contacts are in their first position to energize said impulse relay and to maintain its contacts picked up momentarily after movement of the coding relay contacts to their second position to thereby cause momentary flow of energy through the track relay winding and thereby pre-

vent operation of said track relay by energy supplied thereto as a result of inductive discharge of the track circuit occurring on interruption of the supply of energy thereto.

10. In a coded track circuit railway signaling system, a code transmitting and receiving means comprising a coding relay having contacts movable between a first and a second position and biased to their first position in which they connect across the rails of a section of railway track a code following relay responsive to energy of normal polarity and a code following relay responsive to energy of reverse polarity, a source of energy of normal polarity which is connected across the section rails when the coding relay contacts are in their second position, an impulse relay having a normally released contact which when picked up connects a source of current of reverse polarity across the section rails in series with the winding of said reverse polarity code following relay provided the contacts of said coding relay are in their first position, means for supplying energy to said impulse relay when the coding relay contacts are in their second position, and means effective when said reverse polarity code following relay is responding to coded energy and the contacts of said coding relay are in their first position to supply to said impulse relay each time the contacts of said reverse polarity code following relay release an impulse of energy effective to momentarily pick up the contacts of said impulse relay.

11. In a coded track circuit railway signaling system, a code transmitting and receiving means comprising a coding relay having contacts movable between a first and a second position and biased to their first position in which they connect across the rails of a section of railway track a code following relay responsive to energy of normal polarity and a code following relay responsive to energy of reverse polarity, a source of energy of normal polarity which is connected across the section rails when the coding relay contacts are in their second position, an impulse relay having a normally released contact which when picked up connects a source of current of reverse polarity across the section rails in series with the winding of said reverse polarity code following relay provided the contacts of said coding relay are in their first position, a first circuit for supplying an impulse of energy to said impulse relay each time the contacts of said reverse polarity code following relay release provided said reverse polarity code following relay is responding to coded energy and the contacts of said coding relay are in their first position, a second circuit over which energy is supplied to said impulse relay whenever the coding relay contacts are in their second position, means associated with said second circuit for delaying release of said impulse relay for a relatively short period on interruption of the supply of energy over said second circuit, and means associated with said first circuit for delaying release of said impulse relay for a longer period on interruption of the supply of energy over said first circuit.
